(57) **ABSTRACT**

Assemblies, apparatuses, and methods to extract or convey a material from a source of the material may include a vacuum generation and sound attenuation assembly. The vacuum generation and sound attenuation assembly may include a compressor housing having a vacuum source, a cooling system, and a vacuum controller. The vacuum source may include a compressor powered by an electric motor and positioned to cause a vacuum flow between the source of the material, and the vacuum generation and sound attenuation assembly. The vacuum generation and sound attenuation assembly may further include a sound attenuation chamber positioned to receive at least a portion of the vacuum flow from, and attenuate sound generated by, the vacuum source. The compressor housing and sound attenuation chamber of the vacuum generation and sound attenuation assembly may be arranged compactly on a common chassis for ease of transport and deployment.

**AIR COMPRESSOR HAVING VACUUM AND
ASSOCIATED METHODS FOR LOADING
AND EXTRACTING MATERIALS**

PRIORITY CLAIMS

This application claims the benefit of and priority to U.S. Provisional Patent Application No. 63/373,289, filed Aug. 23, 2022, and titled “AIR COMPRESSOR HAVING VACUUM AND ASSOCIATED METHODS FOR LOADING AND EXTRACTING MATERIALS,” the contents of which are incorporated herein by reference in their entirety.

This is a continuation-in-part of U.S. Non-Provisional application Ser. No. 17/811,277, filed Jul. 7, 2022, titled, “SYSTEMS, METHODS, AND DEVICES FOR INDUSTRIAL TOWER WASTE EXTRACTION,” which claims priority to and the benefit of U.S. Provisional Application No. 63/367,570, filed Jul. 1, 2022, titled “HIGH VOLUME INDUSTRIAL VACUUM ASSEMBLIES AND METHODS,” U.S. Provisional Application No. 63/367,219, filed Jun. 29, 2022, titled “RECEIVER, ASSEMBLIES, AND METHODS FOR LOADING AND EXTRACTING PRODUCT IN ELEVATED TOWER,” U.S. Provisional Application No. 63/367,218, filed Jun. 29, 2022, titled “ASSEMBLIES AND METHODS FOR MATERIAL EXTRACTION FROM RETENTION COLLECTIONS,” U.S. Provisional Application No. 63/364,630, filed May 13, 2022, titled “ASSEMBLIES, APPARATUSES, SYSTEMS, AND METHODS FOR MATERIAL EXTRACTION AND CONVEYANCE,” U.S. Provisional Application No. 63/264,101, filed Nov. 16, 2021, titled “ASSEMBLIES AND METHODS FOR MATERIAL EXTRACTION,” U.S. Provisional Application No. 63/264,015, filed Nov. 12, 2021, titled “ASSEMBLIES AND METHODS FOR MATERIAL EXTRACTION,” U.S. Provisional Application No. 63/203,147, filed Jul. 9, 2021, titled “SYSTEMS, METHODS, AND DEVICES FOR INDUSTRIAL TOWER WASTE EXTRACTION,” and U.S. Provisional Application No. 63/203,108, filed Jul. 8, 2021, titled “SYSTEMS, METHODS, AND DEVICES FOR INDUSTRIAL TOWER WASTE EXTRACTION,” the disclosures of all of which are incorporated herein by reference in their entireties.

This application is also a continuation-in-part of U.S. Non-Provisional application Ser. No. 17/811,293, filed Jul. 7, 2022, titled, “ASSEMBLIES AND METHODS FOR MATERIAL EXTRACTION,” which claims priority to and the benefit of U.S. Provisional Application No. 63/367,570, filed Jul. 1, 2022, titled “HIGH VOLUME INDUSTRIAL VACUUM ASSEMBLIES AND METHODS,” U.S. Provisional Application No. 63/367,219, filed Jun. 29, 2022, titled “RECEIVER, ASSEMBLIES, AND METHODS FOR LOADING AND EXTRACTING PRODUCT IN ELEVATED TOWER,” U.S. Provisional Application No. 63/367,218, filed Jun. 29, 2022, titled “ASSEMBLIES AND METHODS FOR MATERIAL EXTRACTION FROM RETENTION COLLECTIONS,” U.S. Provisional Application No. 63/364,630, filed May 13, 2022, titled “ASSEMBLIES, APPARATUSES, SYSTEMS, AND METHODS FOR MATERIAL EXTRACTION AND CONVEYANCE,” U.S. Provisional Application No. 63/264,101, filed Nov. 16, 2021, titled “ASSEMBLIES AND METHODS FOR MATERIAL EXTRACTION,” U.S. Provisional Application No. 63/264,015, filed Nov. 12, 2021, titled “ASSEMBLIES AND METHODS FOR MATERIAL EXTRACTION,” U.S. Provisional Application No. 63/203,147, filed Jul. 9, 2021, titled “SYSTEMS, METHODS, AND DEVICES FOR INDUSTRIAL TOWER WASTE EXTRACTION,” and U.S. Provisional Application No. 63/203,108, filed Jul. 8, 2021, titled “SYSTEMS, METHODS, AND DEVICES FOR INDUSTRIAL TOWER WASTE EXTRACTION,” the disclosures of all of which are incorporated herein by reference in their entireties.

U.S. Provisional Application No. 63/203,108, filed Jul. 8, 2021, titled “SYSTEMS, METHODS, AND DEVICES FOR INDUSTRIAL TOWER WASTE EXTRACTION,” the disclosures of all of which are incorporated herein by reference in their entireties.

This application is also a continuation-in-part of U.S. Non-Provisional application Ser. No. 17/811,295, filed Jul. 7, 2022, titled, “ASSEMBLIES, APPARATUSES, SYSTEMS, AND METHODS FOR MATERIAL EXTRACTION AND CONVEYANCE,” which claims priority to and the benefit of U.S. Provisional Application No. 63/367,570, filed Jul. 1, 2022, titled “HIGH VOLUME INDUSTRIAL VACUUM ASSEMBLIES AND METHODS,” U.S. Provisional Application No. 63/367,219, filed Jun. 29, 2022, titled “RECEIVER, ASSEMBLIES, AND METHODS FOR LOADING AND EXTRACTING PRODUCT IN ELEVATED TOWER,” U.S. Provisional Application No. 63/367,218, filed Jun. 29, 2022, titled “ASSEMBLIES AND METHODS FOR MATERIAL EXTRACTION FROM RETENTION COLLECTIONS,” U.S. Provisional Application No. 63/364,630, filed May 13, 2022, titled “ASSEMBLIES, APPARATUSES, SYSTEMS, AND METHODS FOR MATERIAL EXTRACTION AND CONVEYANCE,” U.S. Provisional Application No. 63/264,101, filed Nov. 16, 2021, titled “ASSEMBLIES AND METHODS FOR MATERIAL EXTRACTION,” U.S. Provisional Application No. 63/264,015, filed Nov. 12, 2021, titled “ASSEMBLIES AND METHODS FOR MATERIAL EXTRACTION,” U.S. Provisional Application No. 63/203,147, filed Jul. 9, 2021, titled “SYSTEMS, METHODS, AND DEVICES FOR INDUSTRIAL TOWER WASTE EXTRACTION,” and U.S. Provisional Application No. 63/203,108, filed Jul. 8, 2021, titled “SYSTEMS, METHODS, AND DEVICES FOR INDUSTRIAL TOWER WASTE EXTRACTION,” the disclosures of all of which are incorporated herein by reference in their entireties.

This application is also a continuation-in-part of U.S. Non-Provisional application Ser. No. 17/811,280, filed Jul. 7, 2022, titled, “ASSEMBLIES AND METHODS FOR MATERIAL EXTRACTION FROM RETENTION COLLECTIONS,” which claims priority to and the benefit of U.S. Provisional Application No. 63/367,570, filed Jul. 1, 2022, titled “HIGH VOLUME INDUSTRIAL VACUUM ASSEMBLIES AND METHODS,” U.S. Provisional Application No. 63/367,219, filed Jun. 29, 2022, titled “RECEIVER, ASSEMBLIES, AND METHODS FOR LOADING AND EXTRACTING PRODUCT IN ELEVATED TOWER,” U.S. Provisional Application No. 63/367,218, filed Jun. 29, 2022, titled “ASSEMBLIES AND METHODS FOR MATERIAL EXTRACTION FROM RETENTION COLLECTIONS,” U.S. Provisional Application No. 63/364,630, filed May 13, 2022, titled “ASSEMBLIES, APPARATUSES, SYSTEMS, AND METHODS FOR MATERIAL EXTRACTION AND CONVEYANCE,” U.S. Provisional Application No. 63/264,101, filed Nov. 16, 2021, titled “ASSEMBLIES AND METHODS FOR MATERIAL EXTRACTION,” U.S. Provisional Application No. 63/264,015, filed Nov. 12, 2021, titled “ASSEMBLIES AND METHODS FOR MATERIAL EXTRACTION,” U.S. Provisional Application No. 63/203,147, filed Jul. 9, 2021, titled “SYSTEMS, METHODS, AND DEVICES FOR INDUSTRIAL TOWER WASTE EXTRACTION,” and U.S. Provisional Application No. 63/203,108, filed Jul. 8, 2021, titled “SYSTEMS, METHODS, AND DEVICES FOR INDUSTRIAL TOWER WASTE EXTRACTION,” the disclosures of all of which are incorporated herein by reference in their entireties.

TECHNICAL FIELD

The present disclosure relates to assemblies, apparatuses, systems, and methods for extracting material from a source of the material and conveying material to a desired location

and, more particularly, to assemblies and methods for extracting material from environments providing sources for the material and conveying material including or using a compressor to generate a vacuum.

BACKGROUND

Certain environments, such as, for example, work sites, industrial sites, commercial sites, residential sites, or natural sites, may often be sources of material that is either deposited or accumulates as a result of operations at the site or through natural accumulation. The deposit or accumulation of the material may be undesirable for a number of reasons, and thus, removal of the material from the site may be desirable or necessary. For example, the presence of the material in sufficient quantities may hinder operations at the site, may present an undesirable environmental condition, and/or may present recycling or remediation opportunities. Traditional approaches to remove the material from the site and/or to deposit the material may be unsatisfactory or suffer from drawbacks for various reasons. For example, the material may include a variety of material types (e.g., packing material, chemical fillers, insulation, etc.) or material forms (e.g., liquids, solids, emulsions, particulates, etc.), and/or the material may be located or positioned such that it is difficult to efficiently extract the material from the site. In some instances, it may be desirable to convey a material to a desired location, for example, in large quantities and/or in an efficient manner. For example, it may be desirable to convey a material to an elevated position relative to a source of the material. In another example, it may be desirable to position an elevated receiving structure relative to a source of the material that is capable of staging and metering the delivery of material. This may be desirable, for example, when supplying material to the top or upper portion of a tower, such as a refinery tower. Traditional methods of extracting and/or conveying material may be impractical, inefficient, unduly time consuming, and/or labor intensive.

Accordingly, Applicant has recognized a desire to provide improved assemblies, apparatuses, systems, and methods for extracting material from a source and/or depositing material at a desired location, including a variety of different materials from a variety of different environments, that may be more practicable, more efficient, less time consuming, and/or less labor intensive. The present disclosure may address one or more of the above-referenced drawbacks, as well as other possible drawbacks.

SUMMARY

As referenced above, it may be desirable to provide enhanced assemblies, apparatuses, systems, and methods for extracting material from a source of the material and/or depositing the material at a desired location, including a variety of different materials from a variety of different environments, that may be more practicable, more efficient, less time consuming, and/or less labor intensive. For example, the intentional generation or production of some materials for desired intermediate or final products may result in the deposit or accumulation of by-product materials that need to be removed from the environment in which the desired products are generated or produced. In some embodiments, the assemblies, apparatuses, systems, and methods may provide enhanced extraction of material to be removed from various environments, such as, for example, work sites, industrial sites, commercial sites, residential sites, natural sites, etc. For example, in some embodiments,

the material may be extracted in a substantially continuous manner and/or may be extracted without significant contamination of the ambient environment with the material or portions thereof. In some embodiments, the assemblies, apparatuses, systems, and methods may provide enhanced conveyance for the efficient delivery of material to be loaded and/or deposited in various environments and/or sites.

In some embodiments, a compressor and vacuum generation assembly to enhance extraction of material from a material source may include a compressor housing, one or more compressors in the compressor housing, and one or more vacuum generators at least partially contained in the compressor housing and configured to receive pressurized fluid from the one or more compressors. The one or more vacuum generators may include a venturi mechanism configured to use a venturi effect to generate a vacuum flow between the material source and the one or more vacuum generators. The compressor and vacuum generation assembly also may include one or more vacuum controllers at least partially contained in the compressor housing and configured to control a vacuum pressure generated by the one or more vacuum generators.

In some embodiments, an extraction assembly to enhance extraction of material from a material source may include a compressor and vacuum generation assembly having a compressor housing and one or more compressors within the compressor housing. The compressor and vacuum generation assembly further may include one or more electric motors connected to the one or more compressors, one or more vacuum controllers, and one or more vacuum generators at least partially contained in the compressor housing and connected to the one or more compressors. The extraction assembly further may include a sound attenuation chamber including an attenuation housing at least partially defining a chamber interior volume positioned to receive at least a portion of the vacuum flow from the one or more vacuum generators and attenuate sound generated by operation of the one or more vacuum generators.

In some embodiments, a method to enhance extraction or conveyance of material from a material source may include positioning a compressor and vacuum generation assembly having a compressor, an electric motor connected to the compressor, and a vacuum controller within a compressor housing. The method further may include positioning a plurality of vacuum generators at least partially within the compressor housing, and powering the compressor, via the electric motor, to generate a pressurized fluid. The method also may include supplying the pressurized fluid to the plurality of vacuum generators and generating a vacuum flow via the plurality of vacuum generators using the pressurized fluid. The method further may include associating a flow path for the vacuum flow between the plurality of vacuum generators and the material source and delivering the vacuum flow via the flow path to the material source. The method also may include controlling, via the vacuum controller, operation of one or more of the electric motor or the compressor. The method further may include extracting at least a portion of material from the material via the vacuum flow to a material collector through which the vacuum flow passes and depositing at least a portion of the extracted material in the material collector. The method also may include passing the vacuum flow into a sound attenuation chamber to reduce a sound level generated by one or more of the vacuum flow or generating the vacuum flow.

Still other aspects and advantages of these exemplary embodiments and other embodiments, are discussed in detail herein. Moreover, it is to be understood that both the

foregoing information and the following detailed description provide merely illustrative examples of various aspects and embodiments and are intended to provide an overview or framework for understanding the nature and character of the claimed aspects and embodiments. Accordingly, these and other objects, along with advantages and features of the present disclosure, will become apparent through reference to the following description and the accompanying drawings. Furthermore, it is to be understood that the features of the various embodiments described herein are not mutually exclusive and may exist in various combinations and permutations.

BRIEF DESCRIPTION OF THE DRAWINGS

The accompanying drawings, which are included to provide a further understanding of the embodiments of the present disclosure, are incorporated in and constitute a part of this specification, illustrate embodiments of the present disclosure, and together with the detailed description, serve to explain principles of the embodiments discussed herein. No attempt is made to show structural details of this disclosure in more detail than may be necessary for a fundamental understanding of the embodiments discussed herein and the various ways in which they may be practiced. According to common practice, the various features of the drawings discussed below are not necessarily drawn to scale. Dimensions of various features and elements in the drawings may be expanded or reduced to more clearly illustrate embodiments of the disclosure.

FIG. 1 is a schematic side view of an example material extraction assembly including an example vacuum generation and sound attenuation assembly, according to embodiments of the disclosure.

FIG. 2 is a schematic side view of another example material extraction assembly including an example vacuum generation and sound attenuation assembly, according to embodiments of the disclosure.

FIG. 3 is a schematic side view of an example material conveyance assembly including an example material receiver and an example vacuum generation and sound attenuation assembly, according to embodiments of the disclosure.

FIG. 4 is a schematic side view of an example material extraction assembly including an example vacuum generation and sound attenuation assembly used to extract material from a lower elevation, according to embodiments of the disclosure.

FIG. 5 is a schematic perspective view of an example material collector, according to embodiments of the disclosure.

FIG. 6 is a schematic side section view of an example material collector, according to embodiments of the disclosure.

FIG. 7 is a schematic end section view of an example material collector, according to embodiments of the disclosure.

FIG. 8 is a block diagram of an example architecture for operating point determination for a material collector of a material extraction assembly, according to embodiments of the disclosure.

FIG. 9A is a schematic side view of an example material collector and an example carrier for transportation and/or orientation of the material collector, according to embodiments of the disclosure.

FIG. 9B is a schematic end view of the example material collector and example carrier shown in FIG. 9A, according to embodiments of the disclosure.

FIG. 10A is a schematic top view of an example vacuum generation and sound attenuation assembly, according to embodiments of the disclosure.

FIG. 10B is schematic side view of the example vacuum generation and sound attenuation assembly shown in FIG. 10A, according to embodiments of the disclosure.

FIG. 10C is schematic side view of an interior of an example vacuum generation and sound attenuation assembly, demonstrating an example layout of components and airflows, according to embodiments of the disclosure.

FIG. 10D is schematic side view of a partial interior of an example vacuum generation and sound attenuation assembly, according to embodiments of the disclosure.

FIG. 10E is schematic end view of the example vacuum generation and sound attenuation assembly shown in FIG. 10A, according to embodiments of the disclosure.

FIG. 10F is schematic side view of a partial interior of an example vacuum generation and sound attenuation assembly, according to embodiments of the disclosure.

FIG. 10G is schematic end view of the example vacuum generation and sound attenuation assembly shown in FIG. 10E, according to embodiments of the disclosure.

FIG. 11 is a schematic view of a portion of an example vacuum generator, according to embodiments of the disclosure.

FIG. 12 is a schematic top perspective view of an example sound attenuation assembly, with example filter media visible, according to embodiments of the disclosure.

FIG. 13 is a schematic end section view of an example sound attenuation chamber, according to embodiments of the disclosure.

FIG. 14 is a block diagram of an example architecture for operating an example sound attenuation chamber of an example material extraction assembly or material conveyance assembly, according to embodiments of the disclosure.

FIG. 15 is a schematic top view of example system including multiple example material extraction assemblies, according to embodiments of the disclosure.

FIG. 16 is a block diagram of example controllers for coordinating substantially continuous material extraction or conveyance, according to embodiments of the disclosure.

FIG. 17A is a block diagram of an example method for extracting material from a source of the material, according to embodiments of the disclosure.

FIG. 17B is a continuation of the block diagram shown in FIG. 17A, according to embodiments of the disclosure.

FIG. 18 is a schematic diagram of an example material extraction controller configured to at least partially control a material extraction assembly or material conveyance assembly, according to embodiments of the disclosure.

DETAILED DESCRIPTION

The drawings include like numerals to indicate like parts throughout the several views, the following description is provided as an enabling teaching of exemplary embodiments, and those skilled in the relevant art will recognize that many changes may be made to the embodiments described. It also will be apparent that some of the desired benefits of the embodiments described may be obtained by selecting some of the features of the embodiments without utilizing other features. Accordingly, those skilled in the art will recognize that many modifications and adaptations to the embodiments described are possible and may even be

desirable in certain circumstances. Thus, the following description is provided as illustrative of the principles of the embodiments and not in limitation thereof.

The phraseology and terminology used herein is for the purpose of description and should not be regarded as limiting. As used herein, the term "plurality" refers to two or more items or components. The terms "comprising," "including," "carrying," "having," "containing," and "involving," whether in the written description or the claims and the like, are open-ended terms, in particular, to mean "including but not limited to," unless otherwise stated. Thus, the use of such terms is meant to encompass the items listed thereafter, and equivalents thereof, as well as additional items. The transitional phrases "consisting of" and "consisting essentially of," are closed or semi-closed transitional phrases, respectively, with respect to any claims. Use of ordinal terms such as "first," "second," "third," and the like in the claims to modify a claim element does not by itself connote any priority, precedence, or order of one claim element over another or the temporal order in which acts of a method are performed, but are used merely as labels to distinguish one claim element having a certain name from another element having a same name (but for use of the ordinal term) to distinguish claim elements.

FIG. 1 is a schematic side view of an example material extraction assembly 10 including an example vacuum generation and sound attenuation assembly 12, according to embodiments of the disclosure. The example material extraction assembly 10 may be configured to extract material from a source of the material. For example, the material extraction assembly 10, in at least some embodiments, may be used for extraction of a variety of different materials from a variety of different environments. For example, the intentional generation or production of some materials for desired intermediate or final products may result in the deposit or accumulation of by-products or other materials used to facilitate the production of the desired products that need to be removed from the environment. In some embodiments, the assemblies, apparatuses, systems, and methods may provide efficient extraction of the material to be removed from various environments, such as, for example, work sites, industrial sites, commercial sites, residential sites, natural sites, etc. The industrial site may include, for example, chemical reaction towers (or other types of reaction vessels) in which chemical reactions are performed to obtain desirable products. Waste material may be generated as a by-product from the chemical reactions.

For example, some types of chemical reactions may utilize a catalyst material to mediate the chemical reactions, for example, by causing the reaction to occur and/or increasing/decreasing a rate at which the reaction occurs, etc. In a chemical reaction tower (see, e.g., FIG. 1), the catalyst material may be loaded into the chemical tower at various tower levels. Other materials, such as, for example, gasses, liquids, etc., may thereafter be introduced into the tower. The presence of the catalyst material may cause, mediate, or otherwise facilitate a desired chemical reaction to generate a desired product. The chemical reaction may cause the reactivity, morphology, or other properties of the catalyst material to change, thereby reducing the ability of the catalyst to perform its function. For example, the catalyst may be used up or otherwise render its presence in the chemical tower undesirable.

In another example, some types of chemical reactions may utilize devices and/or materials to facilitate the chemical reactions. For example, a packing material may increase the surface area and number of edge surfaces over which the

reaction occurs to improve reaction efficiency and/or to increase/decrease a rate at which the reaction occurs, etc. In a chemical reaction tower (see, e.g., FIG. 1), the facilitating material may be, for example, pall rings that may be loaded into the chemical tower at various tower levels and distributed as packing. The pall rings may include and/or be formed from one or more of metal, ceramic, or polymeric materials. The pall rings may have one or more of any known pall ring sizes, configurations, and/or geometries.

The chemical reaction may also interact with the materials out of which the chemical reaction tower is formed. For example, some chemical reaction towers may be formed from concrete and steel. Chemical reaction towers may be formed from any number and types of materials. The catalyst or the other materials in the chemical reaction tower may react or otherwise interact with these materials of the chemical reaction tower, forming additional undesired products, which may be referred to as "tower products."

The undesired reaction products and/or the tower products, which may be referred to as "waste material," may move within the chemical reaction tower. For example, some of this material may partially or completely cover the catalyst or other important features of the chemical reaction tower, thereby reducing the effectiveness of the catalyst, for example, even in cases where the catalyst is not depleted but remains active.

In some examples, the undesired reaction products and/or the tower products, the "waste material," may partially or completely cover the packing material (e.g., the pall rings) or other important features of the chemical reaction tower, thereby reducing the effectiveness of the packing material. This accumulation may inhibit the reactions of the chemical reaction tower, for example, even in instances where the packing material itself is not depleted or damaged.

The presence of the depleted catalyst material, catalyst or packing material covered in waste material, and/or the waste material itself, may impair future functioning of the chemical reaction tower. For example, the presence of this material in the chemical reaction tower may reduce the conversion efficiency (e.g., the quantity of desirable products produced versus the quantity of input products) of the chemical reactions, increase a reaction time, may render the chemical reactions more difficult to control (or prevent them from occurring), and/or may otherwise reduce the ability of the chemical reaction tower to perform its intended function.

Some embodiments disclosed herein may relate to assemblies, apparatuses, systems, and methods for extracting material from a source of the materials, such as, for example, removing undesired material from environments, such as, for example, industrial environments. In some embodiments, the extracted material may include one or more of catalyst, pall rings, beads, balls, pellets, sand, or bricks. Embodiments may also relate to assemblies, apparatuses, systems, and methods for conveying and depositing new and/or recycled material from a source of the material. In some embodiments, the conveyed or deposited material may include one or more of catalyst, pall rings, beads, balls, pellets, sand, or bricks. For example, some embodiments disclosed herein may facilitate extraction of undesired materials or deposition of new and/or recycled material from or to an industrial environment using, for example, a high-pressure vacuum flow. Removing undesired material from an industrial environment using a high-pressure vacuum flow may provide for time-efficient removal of the undesired materials and/or may reduce or prevent contamination of the ambient environment with the undesired material or portions thereof. Similarly, depositing new and/or recycled materials,

such as packing material, using a high-pressure vacuum flow may provide for time-efficient replacement of said materials in the industrial environment.

Industrial environments, chemical reaction towers, and the associated material discussed herein are merely examples, and other types of environments and/or other types of materials are contemplated.

FIG. 1 schematically depicts an example material source that is an example reaction vessel 14. Reaction vessels 14 may generate desirable products by reacting multiple materials with each other. Once a desirable product is generated, the reaction vessel 14 may be contaminated with the presence of material, which may include undesired material 16 (e.g., waste material, used catalyst, used pall rings, etc.). Applicant has recognized that the undesired material 16 may be distributed throughout the reaction vessel 14, that reaction vessel 14 may be tall, and/or that the reaction vessel 14 may provide limited access to the location or locations of the undesired material 16. For example, as shown in FIG. 1, the reaction vessel 14 may include a plurality of zones 18, which may include the presence of the undesired material 16. The plurality of zones 18 may be located in different regions of the reaction vessel 14, may be separated by different floors, levels, or support members, such as, for example, platforms, beams, etc., of the reaction vessel 14. This may render it difficult to access the undesired material 16 for removal from the reaction vessel 14. In some instances, different zones 18 of reaction vessel 14 may only be accessible using a ladder, scaffolding, or other types of elevated support structures that may render access to the zones challenging.

As schematically depicted in FIG. 1, the material extraction assembly 10 and related methods, according to at least some embodiments, may facilitate extraction of material such as the undesired material 16 from the source of the material, such as the reaction vessel 14, using one or more high-pressure vacuum flows. The use of high-pressure vacuum flows may facilitate extraction of the undesired material 16 (and/or other material), for example, in situations in which there is limited physical access to the plurality of zones 18, where the undesired material 16 may be present. The use of high-pressure vacuum flows may facilitate parallel removal of the undesired material 16 from multiple locations within the source of the material, such as the reaction vessel 14.

For example, as shown in FIG. 1 and FIG. 2, the reaction vessel 14 may include a plurality of reaction vessel ports 24, which may provide only limited access to the plurality of zones 18 from exterior the reaction vessel 14. For example, the reaction vessel ports 24 may be relatively small, such that it may be difficult or impossible for a person to enter the interior of the reaction vessel 14 through the reaction vessel ports 24, or such that it may be difficult or impossible to pass conventional tools, such as shovels or material transportation carts, through the reaction vessel ports 24.

In some embodiments, the material extraction assembly 10 may be configured to efficiently extract the undesired material 16 through the reaction vessel ports 24, for example, by generating a high-pressure vacuum flow and associating the high-pressure vacuum flow to external portions of respective reaction vessel ports 24. In some embodiments, the high-pressure vacuum flow may generate suction directed out of the interior of reaction vessel 14 through the respective reaction vessel ports 24. The suction may generate a vacuum-induced vacuum flow 26 with at least a portion of the undesired material 16 entrained in the vacuum-induced vacuum flow 26.

11

Depending on, for example, the distribution of the undesired material 16, various fixtures may be attached to the reaction vessel ports 24 to control application of suction to the undesired material 16. In some embodiments, conduits, such as hoses or other fluid flow directing carriers may be pneumatically connected to one or more of the reaction vessel ports 24 (see FIG. 2), for example, inside of the reaction vessel 14. The conduits may be positioned such that the vacuum flow 26 entrains desired quantities of the undesired material 16 in the vacuum flow 26. Exterior portions of the reaction vessel ports 24 may be connected to other components of the material extraction assembly 10, for example, to apply the high-pressure vacuum and/or process undesired material 16 entrained in the vacuum flow 26.

Applicant has recognized that the undesired material 16 may be heterogeneous in nature and/or may include material that ranges in size from particulates to one or more inches in size. The undesired material 16 may also be in various states of matter. For example, some portions of the undesired material 16 may be solid, and other portions may be liquid or semi-liquid. Conventional approaches to material removal may be unable to effectively process heterogeneous undesired materials. In some embodiments, the material extraction assembly 10 may facilitate extraction of heterogeneous undesired material, for example, using the high-pressure vacuum flow 26. In some embodiments, the high-pressure vacuum flow 26 may be capable of moving a broad range of materials in various states of matter. The use of a high-pressure vacuum flow 26 for material extraction may facilitate substantial containment of removed undesired material 16, thereby limiting or preventing release into or contamination of the ambient environment with portion of the extracted undesired material 16.

The example material extraction assembly 10 shown in FIG. 1 may be used to extract undesired material 16 from various environments. While described with respect to an industrial environment, at least some embodiments may be used to remove undesired material 16 from other environments, including, for example, commercial, residential, and natural environments. In one such example, the example material extraction assembly 10 may be used to extract or harvest liquid, solid, and semi-solid materials from retention ponds (not shown) and other retention reservoirs for disposal. The retention reservoir may accumulate, for example, runoff, waste, pollutants, sediment, and other matter from higher elevation surfaces. FIG. 4 illustrates how the high-pressure vacuum flow 26 may be used to manage and remove accumulated material along a flow path to separate it from the retention reservoir (not shown).

As shown in FIG. 1 and FIG. 2, the example material extraction system 10 may use a high-pressure vacuum flow 26 to extract materials from an industrial environment. For example, the high-pressure vacuum flow 26 may move the undesired material 16 along a flow path to separate it from the industrial environment. Once separated from the industrial environment, in some embodiments, the undesired material 16 may be transported to a site remote from the industrial environment, for example, for disposal, recycling, and/or remediation. In some embodiments, for example, as shown in FIG. 1, the material extraction assembly 10 may include a compressor and vacuum generation assembly 13, a sound attenuating chamber 40 connected to the compressor and vacuum generation assembly 13, and a material collector 36. The compressor and vacuum generation assembly 13 may include a compressor housing 37 containing at least a vacuum source 38 and a fluid source 42. The fluid source 42 may be, for example, a compressor or other device config-

12

ured to provide pressurized fluid to the vacuum source 38. In some embodiments, one or more of the material collector 36, the compressor and vacuum generation assembly 13 containing the vacuum source 38 and the fluid source 42, or the sound attenuation chamber 40 may be configured to be easily transported between geographical locations for use at different environments. Packaging multiple pieces of the compressor and vacuum generation assembly 13, such as the vacuum source 38, fluid source 42, and other components (see, e.g., FIG. 10A-FIG. 10F) together within the compressor housing 37 may allow the material extraction system 10 to have a more compact footprint. A smaller footprint may allow the material extraction system 10 to, for example, be supported on one or more trailers including wheels, tracks, skids, or other devices for facilitating movement between geographical locations, and to occupy less space at those locations.

In some embodiments, one or more of the material collector 36, the compressor and vacuum generation assembly 13, or the sound attenuation chamber 40 may be arranged to form a flow path beginning at the source of the material (e.g., at the reaction vessel 14) and terminating at the sound attenuation chamber 40. The flow path may be used to extract undesired material 16 from the reaction vessel 14 and, in some embodiments, limit contamination of the ambient environment. For example, the vacuum source 38 may generate a vacuum in the flow path, thereby generating a fluid flow along the flow path. The fluid flow may be used to apply suction proximate the undesired material 16 in the reaction vessel 14 to draw the undesired material 16 into the flow path. The fluid flow in the flow path may cause the undesired material 16 to flow out of reaction vessel 14 and into material collector 36, thereby separating at least a portion of the undesired material 16 from the environment. In some embodiments, a major portion of the undesired material 16 may be deposited in the material collector 36. In some embodiments, a minor portion of the undesired material 16 may flow from the material collector 36, through the vacuum source 38, and into the sound attenuation chamber 40. In some embodiments, the sound attenuation chamber 40 may be configured to remove (or reduce) the minor portion of the undesired material 16 in the fluid flow prior to the fluid flow being exhausted into the ambient environment.

In some embodiments, to form the flow path, the material collector 36 may be pneumatically connected to the source of the undesired material (e.g., the reaction vessel 14). In some embodiments, the pneumatic connection between reaction vessel 14 may be formed using a suction manifold 44 and/or other conduit 46. The suction manifold 44 may be connected to a material collector 36, as shown in the example in FIG. 1, or the suction manifold 44 may be connected to multiple reaction vessel ports 24 of the reaction vessel 14, thereby pneumatically connecting the material collector 36 to multiple locations of the reaction vessel 14. For example, the interior of the material collector 36 may be pneumatically connected to the reaction vessel 14. Pneumatically connecting the material collector 36 to a single location on the reaction vessel 14, may direct the full suction force along a single flow path. Alternately, pneumatically connecting the material collector 36 to multiple locations of reaction vessel 14, as shown in the example in FIG. 2, may facilitate extraction of undesired material 16 from each of the locations, for example, concurrently, simultaneously, sequentially, in parallel, etc.

Some reaction vessels 14 may be tall. Due to the height of some reaction vessels 14 and the distribution of the zones 18 along the height, it may be challenging to access one or

13

more of the zones of the reaction vessel 14. In some embodiments, the suction manifold 44 may include relatively rigid piping (e.g., poly pipe or polyethylene pipe). The piping may render the manifold 44 at least partially self-supporting, which may facilitate pneumatic connection of the suction manifold 44 to an elevated material receiver and/or to multiple zones of the reaction vessel 14. The suction manifold 44, in some embodiments, may pneumatically connect the material collector 36 to any number of locations on the reaction vessel 14, for example, such as those that are difficult to reach or access. The piping may be of low weight and/or easily attachable to a wide variety of structures, which may reduce the need for significant in-person access to difficult-to-reach locations on/in the reaction vessel 14 to extract undesired material 16.

In some embodiments, the suction manifold 44 may be pneumatically connected to the material collector 36, for example, via a conduit 46, such as a hose. In some embodiments, the conduit 46 may be flexible to allow for pneumatic connection of the suction manifold 44 and the material collector 36 in various orientations and positions with respect to one another. The conduit 46 may be sized so as not to limit the flow of fluid along the flow path.

Although the example suction manifold 44 is shown in FIG. 1 as only being pneumatically connected to one material collector 36, in some embodiments, the suction manifold 44 may be connected to multiple material collectors, and/or multiple suction manifolds may be connected to one or more material collectors. In some embodiments, the multiple material collectors may be connected in parallel to, for example, scale-up the extraction capacity of the material extraction assembly 10, for example, by increasing the pressure of the high-pressure vacuum flow, etc., for example, as shown in FIG. 15.

In some embodiments, the undesired material 16 may flow into the material collector 36 after flowing through the suction manifold 44. A major portion of the undesired material 16 may be collected in the material collector 36. In some embodiments, however, some (e.g., a minor portion) of the undesired material 16 may flow out of the material collector 36 in the flow path of the high-pressure vacuum flow 26 through one or more conduits 31. In some embodiments, the material collector 36 may remove a major portion of the undesired material 16 from the fluid flow it receives along the flow path of the vacuum flow 26. In some embodiments, the material collector 36 may receive all, or a portion, of the fluid flow out of the reaction vessel 14, and the material collector 36 may include one or more structures configured to trap a major portion of the undesired material 16 in the fluid flow received inside the material collector 36. Once trapped, the major portion of the undesired material 16 may be retained in the material collector 36, for example, for disposal, recycling, and/or remediation.

Applicant has recognized that it may be desirable to rapidly convey materials in large quantities and/or in an efficient manner to desired locations, for example, that may present unique challenges. For example, it may be difficult to rapidly convey large quantities of materials to an elevated position relative to a source or supply of the material. Although liquid materials may be pumped to elevated positions using conventional pumps, other types of materials, such as semi-solid materials, sludge, particulates, sand, gravel, and discrete solid materials of regular or irregular sizes and shapes may be difficult efficiently to convey to elevated locations.

For example, environments similar to the example environment illustrated in FIG. 1 may present a desire to convey

14

a material to an elevated position relative to a source or supply of the material. For example, it may be desirable to replace the undesired material 16 that was extracted from the reaction vessel 14, for example, as described with respect to FIG. 1, with a material, such as regenerated or new material. For example, it may be desirable to re-supply the reaction vessel 14 with material 16, which may be, for example, fresh or regenerated catalyst, packing materials such as pall rings, and/or other materials after the undesired material 16 has been removed. Assemblies, apparatuses, systems, and methods similar to the embodiments illustrated in FIG. 3 may provide for rapid deployment of desired materials in environments, for example, such as the example environment shown in FIG. 1.

FIG. 3 schematically depicts embodiments where the example reaction vessel 14 is the desired location for depositing a material 16, for example, new, regenerated, and/or recycled material. In some embodiments, a material conveyance assembly 11 may be configured to rapidly and/or efficiently convey the material 16 to an elevated material receiver 45 having a material discharge outlet 43 or port and into the interior of the reaction vessel 14, for example, by generating a high-pressure vacuum flow and associating the high-pressure vacuum flow to external portions of the reaction vessel 14. In some embodiments, depending on, for example, the layout of the reaction vessel, or the distribution of the undesired material 16, it may be more efficient or otherwise advantageous to extract the undesired material 16 from a single exit pathway. For example, as shown in FIG. 1, the reaction vessel 14 may be fitted with a material receiver 45 approximate the top of the reaction vessel 14. The material receiver 45 may, for example, be fastened or otherwise affixed to an upper surface or platform of the reaction vessel 14 and pneumatic access to the interior of the reaction vessel 14 gained through a manhole or other opening in the upper surface. In some embodiments, the high-pressure vacuum flow may generate suction directed out of the interior of reaction vessel 14 through the material receiver 45 with at least a portion of the undesired material 16 entrained in the vacuum-induced fluid flow 26. A centralized flow path thrush the material receiver 45 may facilitate parallel removal of the undesired material 16 from multiple locations (e.g., zones 18) within the source of the material, such as the reaction vessel 14.

In some embodiments, the high-pressure vacuum flow may generate suction directed through a conveyance manifold 41 and a suction manifold 44 external to the reaction vessel 14. The suction may generate a vacuum-induced vacuum flow 26 (as schematically represented by the arrows in FIG. 3), such that new and/or recycled material 16 may be drawn from a material source 39 through the conveyance manifold 41 and directed to, for example, a material receiver 45. The vacuum flow may be induced through a vacuum source 38 of a compressor and vacuum generation assembly 13. The conveyance manifold 41 may provide a path through which the vacuum flow 26 passes to transport the material 16 to the elevated position of the material receiver 45 above the reaction vessel 14.

In some embodiments, the material conveyance assembly 11 shown in FIG. 3 may include one or more parts and/or assemblies in common with a material extraction assembly, such as, for example, the material extraction assembly 10 shown in FIG. 1. In some such embodiments, at least some portions of the material extraction assembly 10 and the material conveyance assembly 11 may be at least substantially interchangeable, facilitating rapid conversion between the material extraction assembly 10 and the material con-

15

veyance assembly 11. This may provide flexibility of use of the material extraction assembly 10 and the material conveyance assembly 11, which may result in efficiencies of use and/or adaptability of use.

The example reaction vessel 14 may be a refinery apparatus including a tower separated internally into various zones 18. The material source 39 may be, for example, a desired source of new, cleaned, regenerated, and/or recycled material. In some examples, the desired material 16 from the material source 39 may be a new and/or regenerated catalyst or similar materials, such as a reaction catalyst. The reaction catalyst may, for example, facilitate a reaction or change the rate at which the reaction occurs. In another example, the material source 39 may be a desired source of new, cleaned, regenerated, and/or recycled packing material such as pall rings, and the pall rings may include and/or be formed from one or more of metal, ceramic, or polymeric materials. The pall rings may have one or more of any known pall ring sizes, configurations, and/or geometries.

The material receiver 45 may be a device configured to rapidly collect conveyed desired materials 16 and deploy the desired materials 16 into an interior of the reaction vessel 14. For example, the material receiver 45 may be positioned at an elevated location relative to the material source 39, for example, toward an upper portion of the reaction vessel 14. The material receiver 45 may have, for example, an internal volume to collect and store amounts of desired material 16 prior to deploying the desired material 16 into the reaction vessel 14. The high-pressure vacuum flow 26 may be directed to the material receiver 45 with the conveyance manifold 41.

The material receiver 45 may include, for example, an aerator, a fluidizer, a porous element (e.g., a screen and/or filter media), a valve, and/or any device or devices capable of separating at least a majority of the desired material 16 from the vacuum flow 26 in the material receiver 45. In some embodiments, desired material 16 received in the material receiver 45 may be pumped, gravity fed, and/or otherwise directed through the material discharge outlet 43 into the interior of the reaction vessel 14.

In some embodiments, the suction manifold 44 may be pneumatically connected to the vacuum source 38, for example, via a conduit 46, such as a hose. In some embodiments, the conduit 46 may be flexible to allow for pneumatic connection of the suction manifold 44 and the vacuum source 38 in various orientations and positions with respect to one another. The conduit 46 may be sized so as not to limit the flow of fluid along the flow path.

Applicant has recognized that some industrial environments, such as the example environments including a reaction vessel 14 shown in FIG. 1 and FIG. 3, may require costly down time for outages and reactor change out. These procedures may involve, for example, removal of the undesired material 16 (e.g., spent catalyst, pall rings, etc.) from the reaction vessel 14 and transferring new, recycled, and/or regenerated material 16 into the reaction vessel 14 prior to resuming operations with the reaction vessel 14. In addition to the down time, physical and environmental hazards, for example, may include limited access due to the size and shape of the reaction vessel 14 (remote locations of the undesired material 16, confined and elevated spaces, sound, etc.), volatile catalyst and reaction by-products from in and around the reaction vessel 14, and contamination risks for the surroundings.

Embodiments of the assemblies and methods disclosed herein may minimize down time from, for example, outages and out and make it safer, faster, and/or less expensive to

16

conduct reactor change out and the processes to extract and convey material from an elevated position above the tower. Disclosed embodiments, for example, provide for one integrated system useable during unloading and reloading of material in a reaction vessel 14, thereby reduce number of lifts and material handling movements (e.g., via crane, forklift, etc.). For example, the material receiver 45, once positioned on top of the reaction vessel 14, completes a pressurized pneumatic circuit (via, at least, suction conduit 44 and/or conveyance conduit 41), whereby the example vacuum generation and sound attenuation assembly 12 may be capable of generating the high-pressure vacuum flow 26 for both unloading and reloading of material in the reaction vessel 14.

Applicant has also realized that, in some embodiments herein, the relatively large volumes of the material source and material collector (for example, compared to bins, drums, or other storage media) may allow more continuous conveyance or extraction flow, with fewer material handling operations or interruptions. This scale may also make transport more economical. For example, referring to FIG. 1, FIG. 2, FIG. 3, and FIG. 4, example compressor housing 37, sound attenuation chamber 40, example material collector 36, and/or material source 39 may all be mounted to a chassis, including trailers or other types of high mobility structures, to enable them to be efficiently transported at scale between geographic locations, for example by truck or rail. Common components necessary for the generation of the high-pressure vacuum flow 26, such as example compressor housing 37 and sound attenuation chamber 40, may be mounted to a common chassis as shown for rapid deployment.

FIG. 5, FIG. 6, and FIG. 7 are schematic views of example material collectors 36, including an example vacuum box 48, according to embodiments of the disclosure when used for collecting waste or undesired material 16 with a material extraction assembly 10. FIG. 5 is a schematic perspective end view of an example material collector 36 including an example vacuum box 48. In some embodiments, the vacuum box 48 may define a structure through which the vacuum flow 26, including entrained undesired material 16, may traverse along the flow path of the vacuum flow 26. In some embodiments, the vacuum box 48 may include a housing 50, and the housing 50 may include one or more walls at least partially defining an interior 52 of the housing 50 (see FIGS. 6 and 7). In some embodiments, the interior 52 may be substantially sealed from the ambient environment by the housing 50, for example, so that a vacuum may be applied to the interior 52, and a flow path through the interior 52 may be established via the vacuum flow 26.

In some embodiments, as shown in FIG. 5 through FIG. 7, a plurality of ports may be provided in/on the housing 50 to facilitate the flow of fluid into and out of the interior 52 of the housing 50. For example, each of the ports may (i) facilitate access to the interior 52, (ii) facilitate connection of conduits or other structures to provide fluid flow through the interior 52 along a flow path with other components of the material extraction assembly 10, and/or (iii) to facilitate removal of portions of undesired material 16 from the interior 52.

For example, the ports may include an inlet port 54, a vacuum port 56, and a discharge port 58. The inlet port 54 may be positioned on the housing 50 and configured to allow access to the interior 52 from outside the housing 50. The inlet port 54 may include an aperture through a wall of the housing 50 that facilitates pneumatic connection of the interior 52 to other components of the material extraction

assembly 10. In some embodiments, the inlet port 54 may be pneumatically connected to the suction manifold 44 (FIGS. 1 and 3) and/or the reaction vessel ports 24 (FIG. 2), for example, to pneumatically connect the interior 52 to one or more of the zones 18 of the reaction vessel 14. When connected, fluid flow including undesired material 16 from the reaction vessel 14 may flow into the interior 52 through the inlet port 54 of the housing 50.

As shown in FIG. 6, in some embodiments, the inlet port 54 may be connected to one or more conduits 60 and/or other fluid flow components to form a flow path to various locations outside the housing 50. In some embodiments, the inlet port 54 may be connected to the one or more conduits 60 to connect a location where the inlet port 54 passes through housing 50 to a location that is more easily accessible for a person to secure pneumatic connections between the inlet port 54 and other components of the material extraction assembly 10. For example, with reference to FIG. 5, the inlet port 54 may extend through a wall of the housing 50 toward the top of the housing 50 and may include conduits 60 to enable the inlet port 54 to be accessible to a person located at a lower portion 62 of the material collector 36.

Applicant has recognized that for applications when undesired material 16 is being extracted from the reaction vessel 14, the vacuum box 48 may be able to store only a limited quantity of material and that the amount of the limited quantity may depend, for example, on how the material is distributed in the interior 52 of the housing 50. For example, if material is deposited in the interior 52 near locations where fluid flow may exit the interior 52, significant quantities of the material in the interior 52 may be drawn out of the interior 52 rather than being retained in the vacuum box 48. The reaction vessel 14 (or other sources of material to be extracted) may include a greater volume of material than the vacuum box 48 is able to hold.

In some embodiments, the vacuum box 48 may be configured to facilitate distribution of material within (e.g., throughout) the interior 52 of the vacuum box 48. Distributing the material in the interior 52 may increase the amount of material that may be retained in the interior 52 without increasing the rate at which the material exits vacuum box 48 due to fluid flow through the interior 52 of the vacuum box 48. This may result in the vacuum box 48 having an increased effective material capacity (e.g., the maximum material capacity at which the quantity of material exiting a structure passes a threshold level) as compared to other structures that do not distribute material throughout their respective interiors. The increased effective material capacity of some embodiments of the vacuum box 48 may reduce the rate at which the vacuum box 48 may need to be replaced as a result of being full due to the use of high-pressure vacuum flow 26 for material extraction. In some embodiments, the vacuum box 48 may facilitate time-efficient replacement in a material extraction assembly, so as to enable the material extraction system to substantially continuously remove undesired material 16 using multiple vacuum boxes 48.

As shown in FIG. 6, in some embodiments, the vacuum box 48 may include a conduit 64 configured to distribute the undesired material 16 within the interior 52 of the vacuum box 48. For example, the conduit 64 may be positioned in the interior 52 and connected to a portion of the inlet port 54 that passes through a wall of the housing 50, so as to position the fluid flow inside the interior 52 of the housing 50. In some embodiments, the conduit 64 may include multiple conduit ports 66 to facilitate distribution of the undesired

material 16 within the interior 52 of the housing 50, for example, by directing the fluid flow from the reaction vessel 14 traveling along the flow path to multiple locations within the interior 52 of the housing 50. The multiple locations may be distributed along the length and/or width of the vacuum box 48, for example, so that the undesired material 16 entrained in vacuum flow 26 is distributed throughout the interior 52 (e.g., rather than being generally deposited at a single location). The conduit ports 66 may be positioned to direct the undesired material 16 in the vacuum flow 26 toward the floor 68 of the housing 50, which may, in some embodiments, be shaped (e.g., V-shaped) to cause the undesired material 16 to flow toward the center of the floor 68, for example, as shown in FIG. 7. In some embodiments, the positioning of the conduit ports 66 may cause a major portion of the undesired material 16 to fall via gravity to the floor 68. For example, by being directed toward floor 68, the undesired material 16 entrained in the vacuum flow 26 may fall below the vacuum port 56, rendering the undesired material 16 less likely to exit the interior 52 of the housing 50 due to the force of gravity.

In some embodiments, the vacuum port 56 may be positioned on the housing 50 to facilitate access to the interior 52 from outside the housing 50, for example, to facilitate the high-pressure vacuum flow 26 to be applied to the interior 52 of the housing 50. The vacuum port 56 may include an aperture passing through a wall of the housing 50 and may allow for the interior 52 to be pneumatically connected to other components of the material extraction assembly 10. In some embodiments, the vacuum port 56 may be pneumatically connected to the vacuum source 38 to enable the vacuum source 38 to apply a vacuum to the interior 52 of the housing 50. The one or more conduits 70 and/or other fluid flow components may form a flow path from the interior 52 to various locations outside the housing 50. In some embodiments, the one or more conduits 70 may be connected at a location where the vacuum port 56 passes through a wall of the housing 50 to a location more easily accessible to a person to make pneumatic connections between the vacuum port 56 and other components of the material extraction assembly 10. For example, as shown in FIG. 5, the vacuum port 56 may extend through a wall of the housing 50 toward the top of the housing 50 and may include conduits 70 to enable the vacuum port 56 to be accessible to a person toward the lower portion 62 of the material collector 36.

In some embodiments, the interior 52 may be placed along the flow path through which the undesired material 16 flows. In some embodiments, the inlet port 54 and the vacuum port 56 may be positioned with respect to the interior 52 of the housing 50 to establish a flow path into and out of the interior 52 of the housing 50. The flow path may cause fluid flow directed into the inlet port 54 to flow through the interior 52 and out the vacuum port 56. The flow path through the interior 52 may be placed along the flow path through the material extraction assembly 10. The flow path may be used in combination with other flow paths, for example, flow paths parallel to one another, to enhance the rate at which undesired material may be removed, to enhance the strength of the applied high-pressure vacuum flow 26 to facilitate removal of materials presenting a challenge to extraction (e.g., materials having a higher viscosity, materials including significant solid content, etc.), or for other purposes, for example, as shown in FIG. 15.

In some embodiments, the vacuum box 48 may be configured to move the undesired material 16 in the interior 52 to reduce the likelihood of it flowing out the vacuum port 56,

which may improve the capacity of the vacuum box 48. For example, the vacuum box 48 may include a material mover 72 configured to move the undesired material 16 within the interior 52, for example, as shown in FIG. 6. Moving the undesired material 16 in the interior 52 may further distribute the undesired material 16 in the interior 52, thereby further increasing the effective undesired material capacity of the vacuum box 48. In some embodiments, the material mover 72 may apply force to various portions of the undesired material 16 in the interior 52 to change the locations of the portions within the interior 52. As shown in FIG. 6, in some embodiments, the material mover 72 may include an auger 74 and a drive unit 76 connected to the auger 74 and configured to drive (e.g., rotate) the auger 74.

In some embodiments, the auger 74 may be positioned in the interior 52 to distribute the undesired material 16 within the interior 52. The auger 74 may include a drill, one or more helical flights, and/or other structures for applying force to the undesired material 16 in the interior 52 of the housing 50. For example, when the auger 74 rotates, a drill or helical flights of the auger 74 may apply force to the undesired material 16 to move it within the interior 52. The movement caused by auger 74 may more evenly distribute the undesired material 16 within the interior 52, for example, to reduce the likelihood of the undesired material 16 flowing out the exhaust port 56. The drive unit 76 may include a motor or other type of actuator usable to rotate the auger 74 by application of a rotational force. In some embodiments, the drive unit 76 may include a hydraulic motor driven using electric power. The quantity of electric power required to rotate auger 74 by the drive unit 76 may be directly related to the quantity of undesired material 16 in the interior 52. For example, as the quantity of undesired material 16 in the interior 52 increases, it may require progressively larger amounts of electric power for the drive unit 76 to rotate the auger 74. As a result, the quantity of electrical power used by the drive unit 76 may be used to determine the load on the auger 74 and/or the quantity of the undesired material 16 in the interior 52 of the housing 50.

To manage the operation of auger 74, in some embodiments, the drive unit 76 may be operably connected to a drive controller 78, which may be coupled to system level controllers. The drive controller 78 may direct, instruct, or otherwise orchestrate operation of the drive unit 76. The drive controller 78 may include computing hardware (e.g., processors, memory, storage devices, communication devices, other types of hardware devices including circuitry, etc.) and/or computing instructions (e.g., computer code) that when executed by the computing hardware cause the drive controller 78 to provide its functionality.

In some embodiments, the drive controller 78 may utilize its computing hardware to set an operating point 77 for the drive unit 76. For example, FIG. 8 is a block diagram of an example architecture for operating point 77 determination for a material collector 36 of a material extraction assembly 10, according to embodiments of the disclosure. For example, to set the operating point 77 of for the drive unit 76, the drive controller 78 may receive information from the drive unit 76 relating to the load placed on the drive unit 76 to drive, for example, the auger 74. For example, drive controller 78 may be configured to monitor the quantity of electric power used by the drive unit 76 to drive the auger 74 over time. For example, the drive unit 76 may communicate one or more signals indicative of its electrical power consumption to the drive controller 78. The drive controller 78 may include a data structure (e.g., a table, list, function, etc., stored in the computer hardware) usable to estimate the

fill level 79 (e.g., a fill level determination 79 as shown in FIG. 8) of the vacuum box 48, for example, based at least in part on the electric power consumption of drive unit 76. For example, the data structure may include a lookup table that provides the fill level 79 of the vacuum box 48 as a function of its electrical power consumption.

To set the operating point 77 of the drive unit 76, in some embodiments, the drive controller 78 may obtain information from one or more sensors 80. For example, the one or 10 more sensors 80 may be positioned at various locations on/in the housing 50 (and/or other locations) and may be operably connected to the drive controller 78 (e.g., in communication with the drive controller 78). The one or more sensors 80 may be configured to generate signals indicative of one or 15 more physical properties, communicating the signals to the drive controller 78, and/or displaying information relating to the physical properties (or quantities determined from the measured physical properties, such as, for example, the fill level 79 of the vacuum box 48). The drive controller 78 may 20 include a data structure (e.g., a table, list, function, etc.) usable to estimate the fill level 79 of the vacuum box 48 based at least in part on the physical properties measured with the one or more sensors 80. The data structure may 25 include a lookup table that provides the fill level 79 of the vacuum box 48 as a function of the measured physical properties. The measured physical properties may include, for example, temperatures, depths/heights of material in the interior 52, opacities of the material, quantities of light reflected by or transmitted through the material, etc.

To measure temperatures, in some embodiments, the vacuum box 48 may include one or more sensors such as thermocouples or other devices for measuring temperature. The one or more sensors 80 may be positioned to measure the temperature of the housing 50, the interior 52, or other 30 components of the vacuum box 48. In some embodiments, the data structure may provide the fill level 79 of the vacuum box 48 as a function of, for example, the temperature of one or more portions of the vacuum box 48.

To measure depths or heights of the undesired material in 40 the vacuum box 48, in some embodiments, the vacuum box 48 may include one or more sensors 80 including depth sensors, such as float sensors, interferometers, etc. The depth sensors may be positioned in the interior 52, on the housing 50, and/or in other locations to measure the height of the 45 undesired material 16 in the vacuum box 48. In some embodiments, the data structure may provide the fill level 79 of the vacuum box 48 as a function of, for example, the heights of the undesired material 16 in the vacuum box 48. In some embodiments, the data structure may also provide 50 the fill level 79 of the vacuum box 48 as a function of, for example, the height of undesired material 16 extracted from a particular zone 18 or region of the material source.

To measure available light, in some embodiments, the vacuum box 48 may include one or more sensors 80 that 55 include photo-sensors (e.g., charge-coupled devices, etc.). The photo-sensors may be positioned to measure the intensity of light reflected by or transmitted by the undesired material 16 in the interior 52 (or other visual indicators), so as to determine the fill level 79 of the vacuum box 48. In some 60 embodiments, the data structure may provide the fill level 79 of the vacuum box 48 as a function of, for example, the measured light intensity of the undesired material 16 in vacuum box 48.

To determine the fill level 79 of the vacuum box 48, in 65 some embodiments, the drive controller 78 receives sensor signals from the one or more sensors 80 using one or more wireless or wired connections. The drive controller 78 may

provide the measurements and/or the load on the drive unit 76 to system level controllers (e.g., supervisory controller(s)) using the one or more wireless or wired connections. The drive controller 78 may use the measurements to determine the fill level 79 of the vacuum box 48 using the data structures. Based on the determined fill level 79 and/or a state of the system (e.g., provided by system supervisory controller(s) 81), the drive controller 78 may determine an operating point 77 for the drive unit 76. The drive unit 76 may consume electric power based on the operating point 77, thereby enabling the drive controller 78 to control the rate at which undesired material 16 is moved within the vacuum box 48.

FIG. 9A is a schematic side view and FIG. 9B is a schematic end view of an example material collector 36 and an example carrier 84 for transportation and/or orientation of the material collector 36, according to embodiments of the disclosure. When in an industrial environment, for example, the vacuum box 48 may be subject to forces applied to it by the environment. To manage these forces, in some embodiments, the vacuum box 48 may include structural housing support members 82 positioned on/in the housing 50. The structural housing support members 82 may be positioned along the length of housing 50 and may at least partially encircle multiple walls of the housing 50. In some embodiments, the structural housing support members 82 may at least partially encircle three or more walls of the housing 48 (e.g., a top wall and two side walls). The structural housing support members 82 may have a thickness that extends away from the housing 50 so as to reduce the likelihood of force being directly transmitted to the housing 50. The structural housing support members 82 may enable the housing 50 to be efficiently repositioned by distributing load for moving the vacuum box 48 across the housing 50. The structural housing support members 82 may also increase the rigidity of the housing 50 (e.g., by enhancing the cross section of the housing 50, where the structural housing support members 82 are connected to the housing 50), thereby allowing the vacuum box 48 to be moved with reduced risk of damage (e.g., due to forces applied to the vacuum box 48 to move it).

In some embodiments, the vacuum box 48 may include a floor 68 having a V-shaped cross-section or other features. Such a floor 68 or other features may tend to make the housing 50 tip to one side or the other side if the housing 50 is placed directly onto a planar surface. To orient the vacuum box 48, in some embodiments, the vacuum box 48 may be provided with a carrier 84, for example, as shown in FIGS. 9A and 9B. The housing 50 and/or the structural housing support members 82 may be positioned on the carrier 84. The carrier 84 may be a structure configured to substantially maintain an upright orientation of the vacuum box 48. The carrier 84 may include a base plate 86 configured to apply force to the vacuum box 48 to move the vacuum box 48 in a manner that is unlikely to damage the vacuum box 48. In some embodiments, lifting member receivers 88 may be positioned on the base plate 86 and may extend into the base plate 86 to allow forks or other structures of heavy equipment to efficiently lift or otherwise apply force to the base plate 86. Forklifts or other types of machinery (e.g., cranes) may be capable of lifting the carrier 84 and the vacuum box 48 using the lifting member receivers 88 (or other features of the vacuum box 48). The support members 82 may be positioned between base plate 86 and the vacuum box 48 to distribute force from the base plate 86 to the vacuum box 48. The vacuum box 48 may have a floor 68 having a V-shaped cross-section, which may tend to cause the vacuum box 48 to list to one side or the other if positioned on a planar

surface. The support members 82 may attach the base plate 86 to the vacuum box 48, so that when the carrier 84 is positioned on a flat surface, the vacuum box 48 is maintained in a predetermined orientation, such as an upright orientation. The base plate 86 may be provided with wheels 90 (and/or tracks and/or skids) to facilitate movement of the vacuum box 48. The wheels 90 may be positioned relative to the base plate 86 to allow the carrier 84 with the vacuum box 48 to roll while being loaded, unloaded, and moved around an environment to which the vacuum box 48 is deployed.

Once the vacuum box 48 is filled with material, it may need to be unloaded before it may continue to be used. For example, extracted material 16 may include spent catalyst and/or used pall rings which may be effectively cleaned or recycled. To facilitate rapid unloading of the vacuum box 48, in some embodiments, the vacuum box 48 may include a door 92 (FIG. 6). The door 92 may substantially extend across one end of the housing 50. The door 92 may enable the interior 52 of the housing 50 to be physically accessed. The door 92 may include a handle 94, which facilitates opening and closing of the door 92. When opened, the end of the housing 50 may be unsealed, thereby allowing for large scale access to the undesired material 16 in the housing 52. When the door 92 is closed, the interior 52 may generally be sealed. The door 92 may allow for efficient removal of undesired material 16 from the interior 52, thereby allowing for a full vacuum box 48 to be quickly emptied and returned to use for undesired material 16 extraction purposes. For example, to efficiently remove undesired material 16 from the interior 52, the door 92 may be opened, and the vacuum box 48 may be oriented, so that gravity force tends to cause material in the interior 52 to exit the housing 50 through the door 92.

FIGS. 10A, 10B, 10C, 10D, 10E, 10F, and 10G are schematic views of example vacuum generation and sound attenuation assemblies 12 according to embodiments of the disclosure. In the examples shown, a compressor housing 37 and a sound attenuation chamber 40 may be adjacently mounted on a common chassis 260. The chassis 260 may have wheels 104 for ease of transport and may also have lift lugs or other hard points for rigging operations, so as to be easily relocated and deployed by operators of the site using a crane, forklift, or other appropriate equipment and/or methods.

FIG. 10A is a schematic top view and FIG. 10B is a schematic side view of an example vacuum generation and sound attenuation assembly 12 according to embodiments of the disclosure. The compressor housing 37 of a compressor and vacuum generation assembly 13 may include components utilized to generate, manage, and/or control the vacuum flow. The compressor housing 37 may include, for example, a hollow interior with an equipment pad for the components and access points for operators of the site to monitor and service the equipment. In some embodiments, one or more doors may be provided on compressor housing 37 to permit access, service, and/or replace components contained in the compressor housing 37.

In some examples, the compressor and vacuum generation assembly 13 may include a fluid source including one or more compressors 264 powered by one or more motors 262 within the compressor housing 37. The one or more compressors 264 may be used to generate a supply of pressurized fluid to provide the vacuum source 38. The one or more compressors 264 may include, for example, a positive displacement rotary screw compressor sized to provide efficient flow of pressurized fluid over extended run

duty cycles, although other compressor types are contemplated. A rotary screw compressor may, for example, have a pair of continuously rotating asymmetric screws to increase the pressure of a working fluid (e.g., air) in a chamber. Operating speeds of the compressor 264 may be varied to meet the vacuum flow requirements of applications, such as those shown the processes in FIG. 1, FIG. 2, FIG. 3, and/or FIG. 4. Applicant has also recognized that the comparatively smooth and quiet operation of a rotary screw compressor may eliminate the need for a specialized foundation or mounting system (for example, a vibration-absorbing base, isolation mount, etc.) to maintain a smaller sized footprint in the compressor housing 37. The one or more compressors 264 may also be powered by one or more prime movers, such as, for example, electric motors 262 suitable for compact and portable operation. For example, the one or more compressors 264 and/or the one or more electric motors 262 may be configured to provide a flow rate of 500 or more cubic feet per minute (cfm), 600 or more cfm, 700 or more cfm, 800 or more cfm, 900 or more cfm, or 1,000 or more cfm, for example, at a pressure of 50 or more pounds per square inch (psig), 60 or more psig, 70 or more psig, 80 or more psig, 90 or more psig, or 100 or more psig.

In some embodiments, the compressor housing 37 may contain other components of the fluid source 42 supporting the operation of the one or more compressors 264. For example, a cooling system 268 may be configured to remove generated heat from the interior of the compressor housing 37. The cooling system 268 may include, for example, one or more after coolers 269. The after coolers 269 may include a heat exchanger to extract heat from the compressed air flow from the compressor 264. In some examples, the one or more after coolers 269 may include one or more heat exchange surfaces (e.g., a plurality of baffles or fins) to distribute heat more evenly. One or more fans 270 may be provided to draw waste heat from the after cooler 269 and force the heat out of the compressor housing 37 through one or more vents 261 in the housing. In some embodiments, the one or more vents 261 (e.g., two or four vents) may be provided in the roof of the compressor housing 37, for example, as shown in FIG. 10A. Alternatively, or in addition, secondary vents 277 may be provided in or on the sides of the compressor housing, for example, as shown in FIG. 10C. The size and/or number of vents 261 may be configured to provide sufficient entry of air from the surroundings for feeding the compressor 264 and/or to provide sufficient cooling for operation of the one or more electric motors 262 and/or the one or more compressors 264. In some embodiments, one or more vents 261 may be provided with louvers and/or a system to prevent dust, debris, and/or water (e.g., rain) from entering through the roof of the compressor housing 37. In some embodiments, the air with condensed moisture from the after cooler 269 may subsequently enter a moisture separator 271 where the air is caused to circulate around the separator body to separate and collect droplets of moisture from the air at the base of the separator by gravity.

In some embodiments, the compressor and vacuum generation assembly 13 may include a vacuum controller 266 within the compressor housing 37, so that operational set points may be controlled during operation (i.e., during continuous conveyance and/or extraction operations when material 16 may not be visible along at least portions of the flow path defined by the high-pressure vacuum flow 26). The vacuum controller 266 may be used to control various operating parameters in the compressor housing 37, such as

motor speed and torque of the electric motor 262, or the volumetric flow rate and supply pressure of the compressor 264.

To control various operating parameters in the compressor 5 housing 37, the vacuum controller 266 may obtain information from one or more sensors 274 (see FIG. 10C) in the housing that monitor operational conditions and provide feedback for the vacuum controller 266. For example, the one or more sensors 274 may be positioned at various 10 locations on/in the housing 50 (and/or other locations) and may be operably connected to the vacuum controller 266 (e.g., in communication with the vacuum controller 266). The one or more sensors 274 may be configured to generate 15 signals indicative of one or more physical and/or environmental properties, communicating the signals to the vacuum controller 266, and/or displaying information relating to the properties (or quantities) determined from the measured physical properties, such as, for example, flow rates, pressures, vapor pressures, moisture levels, temperatures, rotational speeds, and other parameters known in the art.

The vacuum controller 266 may be in communication 20 with and control one or more valves through the compressor and vacuum generation assembly 13. The valves may 25 include, but are not limited to, intake valves, blow down valves, thermal valves, minimum pressure valves, pressure relief valves, solenoid valves, etc. The vacuum controller 266 may control the one or more valves to adjust or tune 30 operation of the compressor and vacuum generation assembly 13. For example, the strength of the vacuum flow 26 generated by the vacuum source 38 may be, for example, substantially proportional to the position of valves controlling a flow rate, pressure, and/or volume of fluid flow from the one or more compressors 264. In addition, the vacuum 35 controller 266 may detect lower volumetric flow rates (for example, 100 cfm or less) and/or pressures during an initial startup of the vacuum source 38 and adjust parameters as necessary to ramp up to a desired flow rate. For example, the one or more electric motors 262 may be variable speed 40 motors, and the vacuum controller 266 may set the amperage for the electric motors 262 during ramp up to prevent current surges which could otherwise trigger fuses or circuit breakers. In another example, the vacuum controller 266 may 45 increase the amperage supplied to the electric motors 262 to prevent a stall in the event measured supply pressures drop below threshold levels during the ramp up.

In some embodiments, the vacuum controller 266 may 50 include computing hardware (e.g., processors, memory, storage devices, communication devices, other types of hardware devices including circuitry, etc.) and/or computing instructions (e.g., computer code) that when executed by the computing hardware cause the vacuum controller 266 to provide its functionality. The vacuum controller 266 may include a lookup table or other data structure usable to determine the setpoint levels to, for example, efficiently extract material from (or convey material to) one or more of the respective zones 18 of the reactor vessel 14.

In some embodiments, a user input device may be provided 55 in communication with the vacuum controller 266. The user input may be communicated to the vacuum controller 266 via the user input device. The user input device may include, for example, one or more buttons, touch sensitive displays, levers, knobs, and/or other devices (e.g., control panels, tablet computers, and/or smart phones) that are operable by personnel to provide the vacuum controller 266 with information for operating and controlling the 60 vacuum flow.

The compressor housing 37 may have ports, unions, and/or other fittings as a junction for fluidic communication between, for example, the vacuum source 38 of the compressor and vacuum generation assembly 13, the material collector 36, the reaction vessel 14, and/or the material source 39 (see, e.g., FIG. 1 and FIG. 3). To transfer the material 16 from the reaction vessel 14 to the material collector 36, as shown in FIG. 1, a high-pressure vacuum flow 26 may be applied to the material collector 36. The high-pressure vacuum flow 26 may be transferred to the material collector 36 through one or more suction outlets 95. In some embodiments, the one or more suction outlets 95 may be a 4-inch diameter coupling, although other sizes and configurations of suction outlet 95 are contemplated. For example, the vacuum flow 26 may be applied to the interior 52 of the material collector 36 via the conduit 96 (or through other types of pneumatic connections between the components). The applied vacuum flow 26 may generate the vacuum-induced fluid flow 26 along the flow path, thereby conveying the undesired material 16 from reaction vessel 14 to material collector 36. Alternatively, or in addition, to convey and deposit material 16 from a material source 39 to the reaction vessel 14, as shown in FIG. 3, a high-pressure vacuum flow 26 may be applied from the suction outlet 95 to the suction manifold 44 pneumatically connected with the conveyance manifold 41 and material source 39.

The compressor housing 37 may have, for example, one or more exhaust outlet ports 272 for the delivery of at least some of the vacuum flow to the sound attenuation chamber 40. Conduits 143 of manifolds or ducts may be used to provide a flow path for the exhaust of the vacuum flow to inlet ports 142 of the sound attenuation chamber 40. The sound attenuation chamber 40 may have alternate configurations and sizes, such as that shown in FIGS. 10F and 10G.

As shown in FIGS. 10A, 10B, 10D, 10E, 10F, and 10G, in some embodiments, the vacuum generation and sound attenuation assembly 12 may include a sound attenuation chamber 40 connected to the vacuum source 38. In some embodiments, the sound attenuation chamber 40 may include an attenuation housing 98 at least partially defining a chamber interior volume being positioned to receive at least a portion of the vacuum flow 26 from the vacuum source 38 and attenuate sound generated by the vacuum source 38 during operation. In some embodiments of the vacuum generation and sound attenuation assembly 12, the vacuum source 38 and the sound attenuation chamber 40 may be connected to one another to form a unified vacuum and attenuation module 100, for example, as shown in FIGS. 1, 2, 3, 4, 10A, 10B, 10D, 10E, 10F, and 10G. In some embodiments, the vacuum source 38 may be directly connected to the sound attenuation chamber 40. In the example embodiment shown, the unified vacuum and attenuation module 100 includes a chassis 260 supporting the vacuum source 38 and the sound attenuation chamber 40, and the chassis 260 may be configured to be transported between geographic locations. In some embodiments, wheels 104 may be connected to the chassis 260 to facilitate transportation, although tracks, skids, etc., may be connected to the chassis 260 instead of, or in addition to, wheels 104, depending, for example, on the type of terrain over which the vacuum and attenuation module 100 may be expected to traverse. In some embodiments, the chassis 260 may be self-propelled, for example, including a powertrain having an engine, hydraulic motor, and/or electric motor. Mounting the vacuum and attenuation module 100 on a mobile chassis 260 may facilitate rapid set-up, removal, and/or reconfigu-

ration of the material extraction assembly 10 in accordance with embodiments of the disclosure.

FIG. 10C illustrates an example of components of the compressor and vacuum generation assembly 13 within the compressor housing 37. In an enclosed or semi-enclosed environment, there may be a high likelihood of generating thermal energy and accumulating moisture. Routing of the exhaust flows, and the expulsion of heat and moisture produced by generating a vacuum flow from the supply of compressed fluid from a compressor, may be important design considerations in industrial vacuum applications. While some amounts of heat and moisture may be anticipated for these applications, accumulation may be costly in terms of maintenance and machinery downtime, which may also hinder productivity.

As shown in FIG. 10C, a compact arrangement of components to maintain spacing within the confines of the compressor housing 37 provide a pattern of circulation and venting to rid the environment of heat and moisture which may be detrimental to the service life of a compressor 264. Applicant has found a space-saving layout of the vacuum generators 106 of the vacuum source 38 with respect to fluid supply ports 116 for flow of the pressurized fluid from the one or more compressors 264 and exhaust flows 143. For example, fluid supply ports 116 and/or associated supply valves for the venturi mechanisms 114 or the vacuum source 38 may enable smaller, more compact compressors 264 to be utilized. The additional free volume within the compressor housing 37 may allow for, for example, better circulation of air and moisture flows 276, 278 within the housing for more efficient cooling and venting than would be possible with other vacuum-generating assemblies.

Additionally, the elevation positioning of the exhaust flow paths 143 from the vacuum generators relative to the suction inlet port 95 may improve efficiency of the compressor and vacuum generation assembly 13. For example, locating the exhaust flow paths 143 to a higher elevation within the compressor housing 37 (see, e.g., locations in FIG. 10D relative to FIG. 10C) relative to the venturi mechanisms 114 and suction inlet port 95 may allow more effective outflow of exhaust and the use of what may otherwise be unused space within the compressor housing 37. As an alternative, the exhaust flow paths 143 may occupy an elevated position on an opposite sidewall of the compressor housing 37. The exhaust flow paths 143 may additionally include openings or vents to eliminate back-pressure.

In some embodiments, the compressor and vacuum generation assembly 13 may include a recirculation fan 273 within the compressor housing 37 to distribute and exhaust heated airflows 276 and moisture 278 generated by the compression and vacuum generation processes. The recirculation fan 273 may rotate at variable speeds so there is sufficient airflow and aeration within the interior volume of the compressor housing 37. As illustrated in FIG. 10C, the recirculation fan 273 may be positioned at a lower elevation in the compressor housing 37 relative to the one or more compressors 264 and the vacuum source 38. From this position, the recirculation fan 273 may direct airflow up and around these components and promote heat flows 276 and excess moisture flows 278 to leave the compressor housing 37 through one or more vents 261, for example, in the roof of the compressor housing 37. As an alternative, the recirculation fan 273 may be positioned at a higher elevation in the compressor housing 37 relative to the one or more compressors 264 and the vacuum source 38 (e.g., near the roof of the housing) to draw air and moisture flows up to exit through the roof. These more central locations for the

recirculation fan 273 above or below the compressors 264 and the vacuum source 38 may allow for the layout and size of other components of the compressor and vacuum generation assembly 13 to be shorter and more compact relative to a recirculation fan positioned, for example, at either end of the compressor housing 37 and directing flows laterally to exit one or more vents on a side of the compressor housing 37. In addition, the vents 261 may have, for example, features such as angled fins or louvres to protect the compressor and vacuum generation assembly 13 from rain, dust, and/or other contaminants external to the compressor housing 37.

In some embodiments, the size and orientation of the vacuum source 38 of the compressor and vacuum generation assembly 13 may allow for the suction and exhaust from the source to be directed in different directions. For example, the one or more suction inlet ports 95 and exhaust outlet ports 272 may be positioned in a substantially lower location in the compressor housing 37, as shown in FIG. 10B, as compared to the substantially elevated location shown in FIG. 10D. Additionally, the one or more suction inlet ports 95 may be positioned at substantially different elevations within the compressor housing 37 than the elevation of the one or more exhaust outlet ports 272. For example, the one or more suction inlet ports 95 may be positioned at an elevation higher than that of the one or more exhaust outlet ports 272. Alternatively, the one or more exhaust outlet ports 272 may be positioned at a higher elevation within the housing relative to the one or more suction inlet ports 95 to use what may otherwise be unused space in the compressor housing 37. Altering the orientation and configuration of the vacuum source 38 may provide a more compact and/or efficient arrangement of the vacuum source 38 (or other components) within the compressor housing 37. Generating the suction for the high-pressure vacuum flow 26 in lower portions of the compressor housing 37, for example, may save additional space within the compressor housing 37 for the circulation and venting of airflow and moisture. In addition, generating the suction for the high-pressure vacuum flow 26 in lower portions of the compressor housing 37, for example, may save additional space for the compressor and vacuum generation assembly 13 on the mobile chassis 260.

In some embodiments, the vacuum controller 266 may be in communication with one or more sensors 274 (see FIG. 10C) within the compressor housing 37 that monitor operational conditions and provide feedback for the controller. The controller 266, for example, may be configured to receive signals and/or remote triggers from the sensors 274. In some examples, the sensors may include one or more thermocouples to measure component surface temperatures, the temperature of airflows 276 circulating within the housing, and/or other temperatures of significance. In response to one or more thermocouple signal(s), the vacuum controller 266 may for example, initiate operation, or increase the rotational speed, of the recirculating fan 273. Alternatively, in response to one or more thermocouple signal(s), the vacuum controller 266 may for example, increase the flow rate through the one or more aftercoolers 269 of the cooling system 268.

The compressor and vacuum generation assembly 13 may also have an air dryer 275 within the compressor housing 37 to remove at least some of the moisture from the flow of compressed fluid. An air dryer 275 may also serve to supplement filters and/or water traps within the assembly. An air dryer 275 may have added benefits in some applications where elevated moisture levels in the environment (for

example, from condensate, suspended water vapor, and other sources) may affect the quality of operations, such as painting, the movement of moisture-sensitive materials such as cement, etc. One or more of the sensors 274 in the compressor housing 37 may be moisture sensors in communication with the vacuum controller 266. In response to one or more signals from the moisture sensors, the vacuum controller 266 may for example, issue commands to initiate operation, or increase the rotational speed, of the recirculating fan 273 to expel moisture flows 278 in the environment from the vents 261.

In some embodiments, the vacuum source 38 may be implemented using a variety of configurations, depending, for example, on the environment to which the material collector 36 is deployed for operation. For example, in some embodiments, the vacuum source 38 may generate a vacuum, which may be applied to the material collector 36. For example, the vacuum source 38 may include one or more vacuum generators 106 configured to generate the vacuum flow 26, and the vacuum generators 106 may be pneumatically connected to one or more material collectors 36, for example, via a conduit 96. In some examples, the one or more vacuum generators 106 may receive at least some electrical power via renewable means, such as batteries, solar panels, wind turbines, and/or other similar sources. In other embodiments, for example, the vacuum source 38 as shown in the arrangement in FIG. 3 may generate a vacuum, which may be applied directly to the suction manifold 44.

The one or more vacuum generators 106 may be configured to generate the vacuum flow 26 in different ways, depending at least in part on, for example, the environment to which the vacuum and attenuation module 100 is deployed. For example, in some embodiments, the vacuum generators 106 may be configured to generate the vacuum flow 26 using the flow of another fluid. For example, the vacuum generators 106 may be connected to a fluid source 42 (for example, the compressor 264). The flow of the pressurized fluid may cause the vacuum generators 106 to generate a high-pressure vacuum flow 26, thereby applying a high-pressure vacuum flow 26 to one or more material collectors 36, which may, in turn, transfer the vacuum flow 26 from the one or more material collectors 36 to the vacuum source 38. The vacuum-induced fluid flow 26 received from the one or more material collectors 36 may include a minor portion of the undesired material 16 from the one or more material collectors 36, for example, as described herein. Alternately or in addition, the flow of the pressurized fluid may cause the vacuum generators 106 to apply a high-pressure vacuum flow 26 to the suction manifold 44, which may, in turn, convey material from the material source 39 to the material discharge outlet 43 of the material receiver 45 located at an elevated position relative to the material source.

When the one or more vacuum generators 106 generate the vacuum flow 26, in some embodiments, the vacuum generators 106 may combine vacuum-induced flow 26 and a fluid supply flow 108 and exhaust the combined flows as a vacuum exhaust fluid flow 110, which may include the minor portion of the undesired material 16, for example, as schematically shown in FIG. 11. To limit or prevent contamination of the ambient environment with the minor portion of the undesired material 16, the vacuum generators 106 may be pneumatically connected to the sound attenuation chamber 40 via a conduit 112 (e.g., a hose). The vacuum exhaust fluid flow 110 may flow from the vacuum source 38 into the sound attenuation chamber 40 via the conduit 112.

Accordingly, the vacuum source 38 may be in the fluid flow path from the reaction vessel 14 to sound attenuation chamber 40.

In some embodiments, in order to generate a more powerful high-pressure vacuum flow 26, multiple vacuum sources 38 and/or one or more sound attenuation chambers 40 may be positioned on a common chassis 260 to form a more powerful vacuum generation and sound attenuation assembly 12 (e.g., a more powerful unified vacuum and attenuation module 100). For example, multiple vacuum sources 38 may each be pneumatically connected to the (one or more) sound attenuation chambers 40, which may cause two (or more) separate flow paths (e.g., for each of the vacuum sources 38) and which may be combined at the one or more sound attenuation chambers 40. In some embodiments, the vacuum sources 38 may be pneumatically connected to a common material collector 36 (e.g., to increase the strength of the high-pressure vacuum flow 26 through the common material collector 36) or different material collectors 36 (e.g., to enable the undesired material 16 to be transferred to multiple material collectors 36 in parallel). In some embodiments, the vacuum sources 38 may be pneumatically connected to the suction manifold 44 (e.g., to increase the strength of the high-pressure vacuum flow 26 through the suction manifold 44) or to multiple inlets in parallel on the suction manifold 44.

In some embodiments, the vacuum source 38 may be implemented using a variety of different structures, depending at least in part on, for example, the environment to which vacuum source 38 is deployed. For example, in some embodiments, the vacuum source 38 may include one or more vacuum generators 106, each having a venturi mechanism 114 configured to receive pressurized fluid from the fluid source 42 (for example, the compressor 264) and use a venturi effect to generate the vacuum flow 26 between the source of the material (e.g., the reaction vessel 14 in FIG. 1 or the material source 39 in FIG. 3) and the vacuum generation and sound attenuation assembly 12. For example, the venturi mechanism 114 may be a vacuum generation mechanism that generates a vacuum using another fluid flow.

In some embodiments, the pressurized fluid supplied by the fluid source 42 to the vacuum generators 106 to generate a high-pressure vacuum flow 26 may have a nominal velocity and a nominal pressure. The pressurized fluid may be directed along a flow path and passed through a restriction in the venturi mechanism 114, constricting the flow of the pressurized fluid and increasing its velocity. The increased velocity of the at least partially choked flow may cause a considerable reduction in the pressure and the drawing of a partial vacuum in that section of the flow path. The high-pressure vacuum flow 26 may thus be generated reliably without any moving parts in the venturi mechanism 114 itself.

Leveraging this phenomenon may increase the capacity and performance of the high-pressure vacuum flow 26 so that, for example, a higher degree of suction may be applied to undesired material 16 in reaction vessel 14, thereby increasing the transfer rate of undesired material 16 from reaction vessel 14 and allowing more difficult material to be transferred out of reaction vessel 14 (FIG. 1). Similarly, a higher degree of suction may be applied to material 16 in a material source 39, thereby increasing the elevation to which material 16 from the material source may be conveyed (e.g., to a receiver 45 at the top of a tall reaction vessel 14) and/or improving the conveyance certain materials 16 (for example, material 16 that is heavier, more viscous, and/or other physical properties) to the reaction vessel 14 (FIG. 3).

As schematically depicted in FIG. 11, which shows an example vacuum source 38 according to embodiments of the disclosure, the venturi mechanism 114 may include fluid supply ports 116 through which the supply of pressurized fluid from the fluid source 42 used to generate the vacuum is received. The venturi mechanism 114 also may include a vacuum port 118 through which the generated vacuum flow may be applied, and an exhaust port 120 through which the fluid flow used to generate the vacuum flow and any material drawn into the vacuum port 118 with the generated vacuum flow may be exhausted from the venturi mechanism 114.

Depending on the application, the vacuum source 38 may combine a number of venturi mechanisms 114 together. For example, the configurations shown in FIG. 10A, FIG. 10B, FIG. 10C, and FIG. 10D may contain a pair of venturi mechanisms 114. Alternatively, the configuration shown in FIG. 10F and FIG. 10G, for example, may contain 40 or more venturi mechanisms 114 (e.g., four venturi mechanisms). The venturi mechanisms 114 may be operated simultaneously in parallel to provide a high-pressure vacuum flow 26 and different levels of vacuum pressure.

In some embodiments, to generate the vacuum flow 26, the fluid supply ports 116 are pneumatically connected a fluid source 42 of the compressor and vacuum generation assembly 13. For example, the fluid supply ports 116 may be pneumatically connected to a compressed fluid stored at or in the fluid source 42. The compressed fluid may be, for example, supplied by the one or more compressors 264 used to generate the fluid supply flow 108 from the fluid source 42. The fluid supply flow 108 may be received through the pneumatic connection and into the fluid supply ports 116. The fluid supply flow 108 may be configured to drive the venturi mechanism 114, thereby generating the vacuum flow 26 produced by the vacuum source 38, which may be applied to other devices via the vacuum port 118.

The strength of the vacuum flow 26 generated by the venturi mechanism 114 may depend at least in part on, for example, the rate of the fluid supply flow 108 used to drive the venturi mechanism 114 and the relative position of the venturi mechanism 114 in the compressor housing 37 relative to the one or more compressors 264. In order to achieve higher vacuum pressure generation, in some embodiments, the vacuum source 38 may include a combiner 122. The combiner 122 may include a manifold for combining multiple fluid supply flows 108 received by the fluid supply ports 116 into a single fluid flow and directing the single fluid flow into the venturi mechanism 114 for generating the vacuum flow 26.

In some embodiments, to manage or control the flow rate, pressure, and/or volume of the fluid supply flow 108 into the venturi mechanism 114, which may be used to control or regulate the strength of the vacuum flow 26, fluid flow control valves 124 may be positioned between the fluid supply ports 116 and the fluid source 42. In some embodiments, the strength of the vacuum flow 26 generated by the venturi mechanism 114 may be substantially proportional to the flow rate, pressure, and/or volume of fluid flow into the fluid supply ports 116. The fluid flow control valves 124 may be used to limit (e.g., reduce, stop, etc.) the rate of fluid flow into the venturi mechanism 114 from the fluid supply ports 116.

In some embodiments, the vacuum port 118 may be pneumatically connected to the one or more material collectors 36 and/or the suction manifold 44 to apply a vacuum to the one or more material collectors 36 and/or suction manifold 44. Applying the vacuum may generate the vacuum-induced fluid flow 26 into the vacuum port 118.

When connected to one or more material collectors 36, the vacuum-induced fluid flow 26 may draw material 16 into the one or more material collectors 36 from the source of the material (e.g., the reaction vessel 14). A major portion of the material 16 may be trapped by and within the material collector 36, and a minor portion of the material 16 may flow into the vacuum source 38 in vacuum-induced fluid flow 26.

To prevent or limit contamination of the ambient environment by a portion of any undesired material 16 which may be extracted, in some embodiments, the exhaust port 120 may be pneumatically connected to the sound attenuation chamber 40. For example, the exhaust port 120 may be pneumatically connected to the sound attenuation chamber 40, which may exhaust the vacuum-induced fluid flow 26, which may include the minor portion of the undesired material 16, and the fluid supply flow 108, for example, as a combined fluid flow into the sound attenuation chamber 40.

In some embodiments, the pneumatic connections between the ports 116, 118, and/or 120 of the vacuum source 38 may be made using conduits, such as hoses or other flexible tubular structures. The conduits may enable the pneumatic connections to be efficiently made, thereby reducing the setup time for assembling the material extraction assembly 10, for example, shown in FIG. 1. In some embodiments, the conduits may include relatively rigid piping (e.g., poly pipe or polyethylene pipe). The piping may render the conduits at least partially self-supporting, for example, when conveying high pressure or high vacuum pressure.

Applicant has recognized that the use of conduits, such as hoses or other flexible tubular structures may present a potential hazard to a person near the conduits. For example, the vacuum flow 26 generated by the vacuum source 38 may cause the conduits to flex or move due to the forces applied to them by the fluid flows. A person may be impacted by the conduits if the flexing or movement of the conduits is significant and/or unexpected. In some embodiments, the material extraction assembly 10 or material conveyance assembly 11 may reduce or eliminate one of more of the conduits, for example, by pneumatically connecting one or more of the components of the material extraction assembly 10 or material conveyance assembly 11 to one another in a manner that eliminates a need for at least some of the conduits (e.g., connecting components directly to one another). For example, the material extraction assembly 10 or material conveyance assembly 11, in some embodiments, may include direct attachment of the vacuum source 38 to one or more material collectors 36, the suction manifold 44, and/or to the sound attenuation chamber 40. By directly attaching the vacuum source 38 to the one or more material collectors 36, the suction manifold 44, and/or the sound attenuation chamber 40, conduits, additional hoses or other flexible structures may not be necessary. As a result, the potential hazard of impact by uncontrolled movement by the conduits or other flexible structures to a person may be reduced or eliminated.

As shown in FIG. 10B, FIG. 10D, and FIG. 10F, in some embodiments, fluidic communication may be provided between the vacuum source 38 in the compressor housing 37 and the sound attenuation chamber 40 to form a unified vacuum and attenuation module 100 on the common chassis 260. Connecting the vacuum source 38 to the sound attenuation chamber 40 may result in the vacuum-induced fluid flow flowing from the vacuum source 38 (e.g., as part of the vacuum exhaust fluid flow 110) directly into the sound attenuation chamber 40. In some such embodiments, both

the vacuum source 38 and the sound attenuation chamber 40 may be rigid structures able to absorb forces applied to them by the vacuum flow 26 without significantly deforming or moving. The unified module 100 may be fitted with lifting receiver members 99 (see FIG. 10E) so the vacuum source 38 and sound attenuation chamber 40 may be easily transported to and deployed by operators of the site using a forklift, crane, or other appropriate equipment and/or methods.

Applicant has recognized that the material 16 may, in some instances, be challenging to move via fluid flow by virtue of, for example, the state of matter of the material 16, the weight of the material 16, the viscosity and/or surface tension of the material 16, and/or other physical properties of the material 16. Such characteristics of the material 16 may limit the rate at which the material 16 may flow through the fluid flow path if only a limited level of the vacuum flow 26 is generated by the vacuum generators 106. In some embodiments, the material extraction assembly 10 or material conveyance assembly 11 may be configured to provide a high-pressure vacuum flow 26, which may be suitable to expedite flow of the material 16 through the fluid flow path. As mentioned, to expedite the flow of the material 16, the vacuum source 38, in some embodiments, may include two or more vacuum generators 106, such as two or more venturi mechanisms 114, which may be operated in parallel with each other in order to enhance the pressure of the vacuum flow 26 generated by the vacuum source 38. Each of the two or more vacuum generators 106 may be driven using the pressurized fluid from the fluid source 42 (and/or other sources of pressurized fluid, such as mobile fluid supplies).

In some embodiments, to manage the pressure generated by vacuum source 38, the venturi mechanisms 114 may be divided into two dual vacuum sources. Each of the venturi mechanisms 114 of the two dual vacuum sources 126 may be fluidly connected in parallel to each other, for example, so that they each may be driven using a common fluid supply port 116, may commonly exhaust out of a common exhaust port 120, and/or may apply vacuum using a common vacuum port 118. In this example manner, each dual vacuum source may provide a higher pressure vacuum flow 26 than may be provided using a single venturi mechanism 114 driven by a similar rate of fluid flow received from the fluid source 42 (e.g., the one or more compressors 264).

To control the generation of the vacuum flow 26 by the one or more vacuum sources 38, in some embodiments, the ports 116, 118, and/or 120 of each dual vacuum source may be controlled by corresponding respective control valves 128, 130. The control valves 128, 130, may be usable to control the rate of fluid flow through each of the respective ports.

In some embodiments, to manage the process of generating the high-pressure vacuum flow, the vacuum controller 266 may be in communication with one or more of the control valves 128, 130. The vacuum controller 266 may be configured to control operation of one or more of the control valves 128, 130 to provide vacuum flows having desired pressures. For example, the vacuum controller 266 may be operably coupled to an adjustor, such as a switch, dial, or other mechanism operable to achieve a desired level of vacuum pressure to be generated by the vacuum source 38. The vacuum controller 266 may use one or more signals from the adjustor to set the operation points for the one or more control valves 128, 130 to generate the desired vacuum pressure with, for example, the venturi mechanisms 114.

The vacuum controller 266 may include computing hardware (e.g., processors, memory, storage devices, communica-

cation devices, other types of hardware devices including circuitry, etc.) and/or computing instructions (e.g., computer code) that when executed by the computing hardware cause the vacuum source controller 136 to provide its functionality. For example, vacuum source controller 136 may modify the quantities of power used to drive control valves 128, 130 to set the quantity of fluid flow through each of the ports 116, 118, and/or 120.

In some embodiments, to limit or prevent contamination of the ambient environment with any undesired material 16 from an extraction process, the sound attenuation chamber 40 may be configured to remove undesired material 16 from the vacuum-induced fluid flow 26 prior to exhaustion into the ambient environment. To do so, the sound attenuation chamber 40 may be pneumatically connected to the vacuum source 38, for example, through conduit 143.

Applicant has recognized that some industrial environments, such as the example environments including a reaction vessel 14 shown in FIG. 1, FIG. 2, and FIG. 3, may include personnel tasked to operate the equipment in these environments. The presence of such personnel may restrict the acceptable level of sound that may be produced for undesired material removal purposes. The sound attenuation chamber 40, according to some embodiments, may be configured to attenuate sound generated by the vacuum source 38 and/or the fluid source 42 to sufficient levels, such that personnel may not need to wear hearing protection due to the sound generated by the material extraction assembly 10 and/or material conveyance assembly 11. In some embodiments, the sound attenuation chamber 40 may be configured to reduce the sound level generated by the material extraction assembly 10 and/or material conveyance assembly 11 by an amount ranging from ten percent to forty percent (e.g., by twenty-five decibels). For example, without the sound attenuation chamber 40, according to some embodiments, the assembly 10, 11 may generate approximately 115 decibels of sound. In contrast, when the sound attenuation chamber 40 is incorporated into the assembly 10, 11, the sound level may be reduced to about 89 decibels.

The sound attenuation chamber 40, in some embodiments, may both filter materials received from fluid flows before exhausting the received fluid flows and attenuate sound from received fluid flows before exhausting the received fluid flows into the ambient environment. In some embodiments, the sound may be attenuated to an extent that personnel in the area need not wear hearing protection, although personnel may need to wear hearing protection for other reasons.

FIGS. 10E and 10G illustrate examples of embodiments of a sound attenuation chamber 40. The sound attenuation chamber 40, in some embodiments, may include an attenuation housing 138 at least partially defining a chamber interior volume 140 positioned to receive at least a portion of the vacuum flow 26 from the vacuum source 38 and attenuate sound generated by the vacuum source 38 during operation. The attenuation housing 138 may substantially seal the interior volume 140 from the ambient environment. The attenuation housing 138 may include one or more walls or other structural members to at least partially seal the interior volume 140.

In some embodiments, to filter undesired material 16 entering the sound attenuation chamber 40, the sound attenuation chamber 40 may include one or more inlet ports 142, one or more discharge ports 144, and/or one or more exhaust ports 146. At least some of the ports may be positioned on the attenuation housing 138 to provide access to the interior volume 140 from outside the attenuation

housing 138. For example, the respective ports may include holes, apertures and/or other structures through one or more walls of the attenuation housing 138 that enable access to interior volume 140.

5 The inlet ports 142 may be pneumatically connected to the vacuum source 38. When pneumatically connected to the vacuum source 38, the inlet ports 142 may receive vacuum-induced flow 26 from the vacuum source 38. The minor portion of the undesired material 16 may be entrained in 10 vacuum-induced flow 26, thereby presenting a potential contamination hazard if exhausted into the ambient environment without further filtering and/or treatment.

The exhaust ports 146, in some embodiments, may be pneumatically connected to the ambient environment. The 15 fluid flow path through the material extraction assembly 10 may end at the exhaust ports 146. Consequently, in some 20 embodiments, vacuum-induced flow 26 drawn from the source of the fluid (e.g., the reaction vessel 14, FIG. 1) and through the flow path may exit the flow path through the 25 exhaust ports 146. The interior volume 140 may be in the flow path between the inlet ports 142 and the exhaust ports 146, such that vacuum-induced flow 26 flows through the 30 interior volume 140 prior to being exhausted into the ambient environment.

25 In some embodiments, to partially attenuate sound, the exhaust ports 146 may be of substantially larger size than the inlet ports 142. The size difference between these ports may 30 reduce or eliminate backpressure on the vacuum-induced flow 26. The flow path may expand greatly in cross-sectional area as the vacuum-induced flow 26 transitions from the inlet ports 142 into the interior volume 140. As a result, any 35 sound generated by the vacuum-induced flow 26 may generally occur at an interface between the inlet ports 142 and the interior volume 140. In some embodiments, accordingly, the sound attenuation chamber 40 may, in part, dissipate the sound generated by the vacuum-induced flow 26 by generating it within the sound attenuation chamber 40, for example, such that the sound will dissipate prior to exiting the sound attenuation chamber 40.

40 In some embodiments, to filter undesired material 16 prior to exhaustion to the ambient environment, the interior volume 140 may include a filter media region 148, as seen in FIGS. 12 and 13. The filter media region 148 may include a portion of the interior volume 140 in which filter media 45 150 may be positioned. The filter media region 148 may be positioned, for example, such that the vacuum-induced flow 26 must substantially flow through the filter media region 148 and filter media 150 prior to being exhausted through the exhaust ports 146 to the ambient environment. In some 50 embodiments, the interior volume 140 may include a filter media support plate 152. The filter media support plate 152 may be configured to support the filter media 150 within the filter media region 148. In some embodiments, the filter media support plate 152 may generally divide the interior 55 volume 140 into two or more sections and may include holes through which the vacuum-induced flow 26 may travel between the sections. One or both sides of the filter media support plate 152 may include one or more baffles 154 configured to attenuate sound. The one or more baffles 154 60 may attenuate sound generated by the vacuum-induced flow 26, for example, prior to exhaustion out of the sound attenuation chamber 40.

In some embodiments, to filter undesired material 16 prior to being exhausted to the ambient environment, the filter media 150 may be configured to filter at least a portion of the minor portion of the undesired material 16 from the vacuum-induced flow 26. The filter media 150 may include any type

of filter media for removing material from fluid flows. The filter media 150 also may be sound absorptive and, in part, help to dissipate the sound generated by the vacuum-induced flow 26. The filter media 150 may, in some examples, exhibit a relatively limited filtration capacity. As filter media 150 filters the undesired material 16, its permeability to fluid flow may decrease.

To manage the filtration capacity of the filter media 150, in some embodiments, the sound attenuation chamber 40 may include one or more jet generators 156 (see FIG. 10E and FIG. 10G) positioned relative to the sound attenuation chamber 40 to generate jets of fluid flow directed toward the filter media 150 to at least partially maintain the filtration capacity of the filter media 150. For example, the jet generators 156 may be positioned to generate jets of fluid flow directed toward the filter media 150 to at least partially refresh or restore the filtration capacity of filter media 150. For example, the jet generators 156 may be positioned outside the attenuation housing 138 and oriented facing into the filter media region 148.

When the jet generators 156 generate the jets, the jets may transfer undesired material 16 filtered by the filter media 150 out of the filter media 150 and into the interior volume 140. This may, in some embodiments, at least partially restore the permeability and/or the filtration capacity of the filter media 150. For example, the jets may cause undesired material 16 trapped in the filter media 150 to drop out of the filter media region 148, for example, through holes in the filter media support plate 152 and into interior volume 140.

To drive the jet generators 156, in some embodiments, the sound attenuation chamber 40 may include a jet fluid supply 158. The jet fluid supply 158 may be configured to store compressed fluid. In some embodiments, the jet fluid supply 158 may include a storage tank in which the compressed fluid is stored. The compressed fluid may be a gas, such as, for example, compressed air. The jet fluid supply 158 may be pneumatically coupled to the jet generators 156. The jet generators 156 may include one or more ports and one or more electrically driven actuators configured to control the rate at which the compressed fluid from the jet fluid supply 158 exits the jet generators 156. Thus, the jet generators 156 may modulate one or more of a strength of the jets of fluid flow, timing of the jets of fluid flow, or one or more other characteristics associated with the jets of fluid flow.

To fill the jet fluid supply 158, in some embodiments, the sound attenuation chamber 40 may include a fluid supply port 160. The fluid supply port 160 may be pneumatically connected to the jet fluid supply 158 to refill the jet fluid supply 158 with compressed fluid, for example, when another source of compressed fluid (e.g., the fluid source 42) is pneumatically coupled to the fluid supply port 160.

In some embodiments, due to a limited size of the interior volume 140, only a finite quantity of undesired material 16 may be stored in the interior volume 140. Over time the interior volume 140 may become filled with undesired material 16 as undesired material 16 is removed from the source of the material (e.g., the reaction vessel 14). Once the interior volume 140 is filled, the sound attenuation chamber 40 may become inoperable, for example, as undesired material 16 may block fluid flow through the interior volume 140.

To manage the fill level 79 of the interior volume 140, in some embodiments, the sound attenuation chamber 40 may include one or more discharge ports 144. The discharge ports 144 may facilitate removal of undesired material 16 from the interior volume 140. In some embodiments, undesired material 16 may be removed from the interior volume 140

through the discharge port(s) 144 while the vacuum-induced flow 26 flows through the interior volume 140.

To remove undesired material 16 from the interior volume 140, in some embodiments, the discharge port 144 may be pneumatically connected to a material collector 36 (e.g., a vacuum box 48). For example, the discharge port 144 may be pneumatically connected to a material collector 36 via a conduit 162 (e.g., such as a restrictive hose). When a high-pressure vacuum is applied to the material collector 36, undesired material 16 in the interior volume 140 may be drawn out of the interior volume 140, through the conduit 162, and into the material collector 36. Thus, both the major portion and the minor portion of the undesired material 16 extracted from the source of the material (e.g., the reaction vessel 14) may be transferred to a material collector 36. The discharge port 144 may be pneumatically connected to other components for undesired material discharge purposes without departing from embodiments disclosed herein.

To control when and/or the rate of removal of the undesired material 16 from the interior volume 140, in some embodiments, the sound attenuation chamber 40 may include a discharge port control valve 164. The discharge port control valve 164 may be positioned to control the rate of fluid flow through the discharge port 144. For example, the discharge port control valve 164 may include an electrically driven actuator usable to control the rate of fluid flow through discharge port 144. In some embodiments, the discharge port control valve 164 may control the rate of fluid flow through discharge port 144 to selectively remove undesired material 16 from the interior volume 140.

To determine when and/or at which rate to remove undesired material 16 from the interior volume 140, in some embodiments, the sound attenuation chamber 40 may include one or more sensors 166. The sensors 166 may be positioned to monitor the filtration capacity of the filter media 150, the fill level 79 of the interior volume 140, and/or the flow rate of undesired material 16 out of the discharge port 144. The sensors 166 may be configured to generate signals indicative of any physical property of the sound attenuation chamber 40 and use the signals to determine these quantities. For example, the sensors 166 may include photo-sensors that measure the filtration capacity of the filter media 150 based on a quantity of light transmitted by the filter media 150. In some embodiments, the sensors 166 may include a transducer configured to measure the mass of undesired material 16 to determine the fill level 79 of the interior volume 140. The sensors 166 may include other components for measuring the same or different types of physical properties without departing from embodiments disclosed herein.

FIG. 14 is a block diagram of an example architecture for operating an example sound attenuation chamber 40 of an example material extraction assembly 10 or an example material conveyance assembly 11, according to embodiments of the disclosure. To coordinate operation of the sound attenuation chamber 40, in some embodiments, the sound attenuation chamber 40 may include a chamber controller 168 in communication with one or more of a discharge port control valve actuator, one or more jet generators 156, and the one or more sensors 166. For example, the chamber controller 168 may be operably connected to the discharge port control valve 164, the jet generators 156, and the sensors 166. The chamber controller 168 may obtain information from sensors 166 and selectively drive the discharge port control valve 164 and/or the jet generators 156 based on the information to ensure that (i) the filter media 150 is capable of continuing to filter fluid flows

through the interior volume **140** and (ii) the interior volume **140** is not overfilled with undesired material **16**.

In some embodiments, the chamber controller **168** may include computing hardware (e.g., processors, memory, storage devices, communication devices, other types of hardware devices including circuitry, etc.), and/or computing instructions (e.g., computer code) that when executed by the computing hardware cause chamber controller **168** to provide its functionality. The chamber controller **168** may include a lookup table or other data structure usable to make an operating points determination **170** for the discharge port control valve **164** and/or the jet generators **156** based at least in part on the fill level **79** and filtration capacity of the filter media **150**. Once the operating points are determined, the chamber controller **168** may be configured to modify operation of the discharge port control valve **164** and/or the jet generators **156** based at least in part on the operating points. For example, the chamber controller **168** may be configured to modify the quantities of power used to drive the discharge port control valve **164** and/or the jet generators **156** to set the quantity of fluid flows through each of the discharge port control valves **164** and/or the jet generators **156**. As a result, in some embodiments, the sound attenuation chamber **40** may be more likely to be able to substantially continuously operate.

In some embodiments, to enable a person to control operation of the sound attenuation chamber **40**, the sound attenuation chamber **40** may include a user input device **172**. The user input device **172** may be in communication with the chamber controller **168**. The user input may be communicated to the chamber controller **168** via the user input device **172**. The user input device **172** may include, for example, one or more buttons, touch sensitive displays, levers, knobs, and/or other devices (e.g., control panels, tablet computers, and/or smart phones) that are operable by a person to provide the chamber controller **168** with information for operating or controlling the sound attenuation chamber **40**.

The chamber controller **168** may be configured to receive information from a person via the user input device **172** regarding how frequently to refresh the filtration capacity of the filter media **150** and/or information regarding how frequently to discharge undesired material **16** from the interior volume **140**. The chamber controller **168** may use such information when determining the operating points for the discharge port control valve **164** and/or the jet generators **156**. For example, a person may provide operational preferences or other information using the user input device **172** to configure operation of the sound attenuation chamber **40**.

In some embodiments, the chamber controller **168** may be powered using electricity. The sound attenuation chamber **40** may include one or more solar panels **174** that provide electrical power to the chamber controller **168**. The chamber controller **168** may include one or more batteries in which power from the one or more solar panels **174** may be stored prior to use by the chamber controller **168** (and/or other controllers of the material extraction assembly **10**).

Applicant has recognized that some environments, such as industrial environments similar to the environment illustrated in FIG. 1, FIG. 2, and FIG. 3, may include volatile hydrocarbon fluids (and/or other types of volatile materials) or other types of fluids susceptible to combustion. Some embodiments of the material extraction assembly **10** or material conveyance assembly **11**, or one or more components thereof, may not be powered by combustible power sources. Rather, the material collector **36**, the vacuum source **38**, the sound attenuation chamber **40**, and/or the fluid

source **42** may be powered with electricity and/or compressed fluid. In some such embodiments, the material extraction assembly **10** or material conveyance assembly **11** may be capable of removing undesired materials from an environment, such as an industrial environment, without the risk of igniting combustible materials in the environment (or with a reduced risk).

To supply pressurized or compressed fluid, the fluid source **42**, such as compressor **264**, may compress fluid and store the compressed or pressurized fluid for future use. In some embodiments, the fluid source **42** may include an air compressor, and the air compressor may be configured to compress air from the ambient environment to generate the compressed or pressurized fluid. The fluid source **42** may compress other fluids without departing from embodiments disclosed herein.

To limit or prevent combustion risk, in some embodiments, the fluid source **42** may compress fluid using electricity. The fluid source **42** may obtain the electricity from any electricity source. In some embodiments, the fluid source **42** received power from the one or more electric motors **262**. In some embodiments, the fluid source **42** may include one or more batteries for providing the electricity to the fluid source **42**. In some embodiments, the fluid source **42** may include a power cable and/or other componentry for obtaining electricity from another source (e.g., from a utility company or other large-scale supplier, a solar setup, and/or other non-combustion-based electricity producers, etc.).

Applicant has recognized that environments, such as industrial environments, such as the sites illustrated in FIG. 1, FIG. 2, and FIG. 3, may benefit from a high uptime by their operators. As a result, the time required to setup the material extraction assembly **10** or material conveyance assembly **11** may be a significant cost to the operators of the site. In some embodiments, the material extraction assembly **10** or material conveyance assembly **11** disclosed herein may provide for the efficient setup, operation, and removal of the assembly in many environments, including industrial environments. In some embodiments, any of the components of the material extraction assembly **10** or material conveyance assembly **11** may be placed or mounted on chassis including trailers or other types of high mobility structures to enable them to be efficiently placed and oriented with respect to, for example, a reaction vessel.

Applicant has recognized that environments, such as the environments shown in FIG. 1, FIG. 2, and FIG. 3, may have different requirements for material removal. For example, different industrial environments may have different quantities of undesired material and/or undesired material at different industrial environments may have different physical properties. The material extraction assembly **10** or material conveyance assembly **11** in accordance with embodiments disclosed herein may provide for rapid deployment of a material extraction assembly **10** or material conveyance assembly **11** that is customized or tailored to meet the requirements of each industrial environment. As a result, different numbers of components may be deployed and connected (e.g., pneumatically connected) in parallel and/or in series to provide desired levels of vacuum strength and/or desired storage capacities for undesired material.

For example, as shown in FIG. 15, in some embodiments, a material extraction assembly **10** may include multiple material collectors **36** (e.g., vacuum boxes **48**), compressor and vacuum generation assemblies **13**, and/or sound attenuation chambers **40**. Each a compressor and vacuum generation assembly **13** may include, for example, multiple vacuum sources **38** and/or fluid sources **42**. Each material

collector 36 may be pneumatically connected to a reaction vessel 14 via a divider 176 and manifold 178 through conduits 180. The divider 176 may be a pneumatic splitter that establishes two separate fluid flow paths through the respective material collectors 36.

By pneumatically connecting both material collectors 36, for example, to the source of the material (e.g., the reaction vessel 14) in parallel, undesired material 16 from the source of the material may be transferred to both material collectors 36 concurrently or substantially simultaneously. As a result, the material extraction assembly 10 may be capable of removing twice as much undesired material 16 before the material collectors 36 are filled. The material removal capacity of a material extraction assembly 10 in accordance with some embodiments may be scaled up (or down) as desired in this example manner to meet environment-based requirements. In such embodiments, any of the components may include any number of ports to facilitate the formation of multiple fluid flow paths. For example, as seen in FIG. 15, the material collectors 36 may include four ports (e.g., two inlet ports and two vacuum ports). The components shown in FIG. 15 may include different numbers of ports without departing from embodiments disclosed herein.

Each material collector 36 may be pneumatically connected to two vacuum sources 38 through hoses 182. By pneumatically connecting two vacuum sources 38 to a single material collector 36, the strength of the high-pressure vacuum in the material collector 36 may be increased. Consequently, a higher degree of suction may be applied to undesired material 16 in reaction vessel 14, thereby increasing the transfer rate of undesired material 16 from reaction vessel 14 and allowing more difficult material to be transferred out of reaction vessel 14. The suction strength of the material extraction assembly 10 (or material conveyance assembly 11 for conveyance applications) in accordance with embodiments may be scaled up (or down) as desired in this example manner to meet environment requirements.

In some embodiments, each of the vacuum sources 38 of the compressor and vacuum generation assemblies 13 may be pneumatically connected to a material collector 36 and/or suction manifold 44 may also exhaust through a corresponding sound attenuation chamber 40. For example, the vacuum sources 38 that exhaust through a corresponding sound attenuation chamber 40 may be positioned on a trailer together to form a mobile unit. In this manner, the material extraction assembly 10 or material conveyance assembly 11 may be quickly and efficiently deployed and scaled up (or down) as desirable to meet environment requirements.

To facilitate efficient reconfiguration of the material extraction assembly 10 or material conveyance assembly 11, any of the pneumatic connections may be implemented using quick connect-disconnect connections and/or pneumatic isolators. The quick connect-disconnect connections may allow for any of the pneumatic connections to be quickly made and removed. The pneumatic isolators may automatically seal the material removal system when a pneumatic connection is disconnected. For example, pneumatic isolators may be positioned between the divider 176 and the material collectors 36. When one of conduits 180 is disconnected from the divider 176, the pneumatic isolator may automatically seal the opening in the divider 176, to which the disconnected conduit was connected. In this manner, the disconnection of a conduit may not impact the other fluid flow paths. For example, the fluid flow path between the divider 176 and the remaining connected material collector 36 (e.g., with the other conduit) may not be impacted. Quick connect-disconnect connections and/or

pneumatic isolators may be used to facilitate the pneumatic reconfiguration of any of the fluidic topologies illustrated throughout this application.

Applicant has recognized that environments similar to the example illustrated in FIG. 1 may need to be filled with desired material after the undesired material 16 has been removed. For example, the reaction vessel 14 may need to be refilled with catalyst, packing materials such as pall rings, or other materials after undesired material 16 is removed. Assemblies, apparatuses, systems, and methods similar to the example illustrated in FIG. 3 and accordance with embodiments disclosed herein may provide for rapid deployment of desired materials in certain environments.

Some embodiments of the material extraction assembly 10 or material conveyance assembly 11 may include a number of components configured to cooperatively operate to provide its functionality. To orchestrate the operation of these components, in some embodiments, the operation of the material extraction assembly 10 or material conveyance assembly 11 may be coordinated in an at least partially automated manner. For example, as explained herein, any of the components of the material extraction assembly 10 or material conveyance assembly 11 may include a supervisory controller 81, which may coordinate operation of one or more of the components.

As shown in FIG. 16, the material extraction assembly 10 or material conveyance assembly 611 may include one or more supervisory controllers 81, which may be in communication with one or more of the drive controller 78 associated with operation of one or more material collectors, a vacuum source controller 136 associated with operation of one or more vacuum sources, and/or a chamber controller 168 associated with controlling operation of one or more sound attenuating chambers 40. The aforementioned supervisory controller(s) and other controllers may be in communication with one another via a network 194. The network 194 may include one or more wired and/or wireless networks through which the supervisory controller(s) 81 and other controllers may communicate.

FIG. 17A and FIG. 17B are a block diagram of an example method 1700 for extracting material from a source of the material, for example, any one or more of the example sources of material described herein, as well as others. The example method 1700 is illustrated as a collection of blocks in a logical flow graph, which represent a sequence of operations. In some embodiments of the method 1700, one or more of the blocks may be manually and/or automatically executed. In the context of software, where applicable, the blocks may represent computer-executable instructions stored on one or more computer-readable storage media that, when executed by one or more processors, perform the recited operations. Generally, computer-executable instructions include routines, programs, objects, components, data structures, and the like that perform particular functions or implement particular data types. The order in which the operations are described is not intended to be construed as a limitation, and any number of the described blocks may be combined in any order and/or in parallel to implement the method.

FIG. 17A and FIG. 17B are a block diagram of an example method 1700 for extracting material from a source of the material, according to embodiments of the disclosure. At 1702 (see FIG. 17A), the example method 1700 may include operating an electric motor to power a compressor of a compressor and vacuum generation assembly inside of a compressor housing as a fluid source to supply pressurized

fluid, for example, as described herein. In some embodiments, the fluid source may include two or more compressors.

The example method 1700, at 1704, may include supplying the pressurized fluid to a vacuum source of the compressor and vacuum generation assembly configured to generate a vacuum flow using the pressurized fluid, for example, as described herein. In some embodiments, one or more conduits may be provided between one or more fluid sources and the vacuum generator to supply pressurized fluid from the one or more fluid sources to the vacuum source, for example, as described herein.

At 1706, the example method 1700, may include generating a vacuum flow via the vacuum source, for example, as described herein. For example, the vacuum source may include a plurality of vacuum generators configured to use the pressurized fluid from the compressor to generate the vacuum flow. In some embodiments, the vacuum source may include two or more, three or more, or four or more vacuum generators. In some embodiments, one or more of the vacuum generators may include a venturi mechanism configured to use the pressurized fluid flow to generate the vacuum flow.

At 1708, the example method 1700 may include controlling operating parameters of at least the electric motor and the compressor via a vacuum controller, for example, as described herein. For example, sensors may be provided upstream and/or downstream of the vacuum source, and a controller may receive sensor signals from the sensors to control the electric motor and the compressor. In some embodiments, the vacuum controller may be configured to compare the parameters determined based at least in part of the sensor signals and compare the values with information stored in memory (e.g., via a look-up table) for different configurations and/or types of materials that may be extracted.

The example method 1700, at 1710, may include determining whether a vacuum pressure of the vacuum flow is in a range sufficient to efficiently draw the material from the material source in a manner similar to those described herein. If, at 1710, it is determined that the vacuum pressure is not sufficient or is too high, the example method 1700 may include at 1712 adjusting one or more of a flow rate or a pressure of the pressurized fluid supplied to the vacuum source. After 1712, the method 1700 may return to 1710 to determine whether the vacuum pressure of the vacuum flow is within the desired range.

If, after 1710, it is determined that the vacuum pressure lies within the desired range, the example method 1700 may include, at 1714, drawing the material from the material source into a material collector to collect extracted material from the material source, for example, as described herein. One or more manifolds and/or conduits and one or more material receivers may be provided between the source of the material and the material collector to convey the extracted material to the material collector, for example, as described herein.

At 1716 (see FIG. 17B), method 1700 may include removing heat from pressurizing the compressed fluid from the compressor housing through a cooling system. In some embodiments, the cooling system may include one or more after coolers and one or more fans, for example, as described herein. In some embodiments, the one or more after coolers may include one or more heat exchange surfaces, such as baffles or fins, and at least some of the waste heat from the after coolers may be blown by the fans through vents in the

housing. The example method 1700, at 1718, may include removing moisture from the vacuum flow, for example, as described herein.

At 1720, the example method 1700 may include collecting a major portion of the extracted material in the material collector, for example, as described herein. At 1722, the example method 2000 may include conveying a minor portion of the extracted material to a sound attenuation chamber via the vacuum flow, for example, as described herein. For example, a conduit may be provided between the material collector and the sound attenuation chamber providing a flow path for the vacuum flow to convey the minor portion of the material (e.g., material not trapped in the material collector) to the sound attenuation chamber.

At 1724, the example method 1700 may include attenuating, via the sound attenuation chamber, sound generated by the vacuum flow and/or generation of the vacuum flow, for example, as described herein. The attenuation may include passing the vacuum flow including the minor portion of the extracted material through filter media associated with the sound attenuation chamber (e.g., at least partially enclosed within the sound attenuation chamber) to capture at least a portion of the minor portion of extracted material in the filter media, for example, as described herein.

It should be appreciated that at least some subject matter presented herein may be implemented as a computer process, a computer-controlled apparatus, a computing system, or an article of manufacture, such as a computer-readable storage medium. While the subject matter described herein is presented in the general context of program modules that execute on one or more computing devices, those skilled in the art will recognize that other implementations may be performed in combination with other types of program modules. Generally, program modules include routines, programs, components, data structures, and other types of structures that perform particular tasks or implement particular abstract data types.

Those skilled in the art will also appreciate that aspects of the subject matter described herein may be practiced on or in conjunction with other computer system configurations beyond those described herein, including multiprocessor systems, microprocessor-based or programmable consumer electronics, minicomputers, mainframe computers, handheld computers, mobile telephone devices, tablet computing devices, special-purposed hardware devices, network appliances, and the like.

FIG. 18 is a schematic diagram of an example material controller 300 configured to at least partially control a material extraction assembly 10 and/or a material conveyance assembly 11, according to embodiments of the disclosure. The material controller 300 may include one or more of the controllers described herein. The material controller 300 may include one or more processor(s) 1800 configured to execute certain operational aspects associated with implementing certain systems and methods described herein. The processor(s) 1800 may communicate with a memory 1802. The processor(s) 1800 may be implemented and operated using appropriate hardware, software, firmware, or combinations thereof. Software or firmware implementations may include computer-executable or machine-executable instructions written in any suitable programming language to perform the various functions described. In some examples, instructions associated with a function block language may be stored in the memory 1802 and executed by the processor(s) 1800.

The memory 1802 may be used to store program instructions that are loadable and executable by the processor(s)

1800, as well as to store data generated during the execution of these programs. Depending on the configuration and type of the material controller **300**, the memory **1802** may be volatile (such as random access memory (RAM)) and/or non-volatile (such as read-only memory (ROM), flash memory, etc.). In some examples, the memory devices may include additional removable storage **1804** and/or non-removable storage **1806** including, but not limited to, magnetic storage, optical disks, and/or tape storage. The disk drives and their associated computer-readable media may provide non-volatile storage of computer-readable instructions, data structures, program modules, and other data for the devices. In some implementations, the memory **1802** may include multiple different types of memory, such as static random access memory (SRAM), dynamic random access memory (DRAM), or ROM.

The memory **1802**, the removable storage **1804**, and the non-removable storage **1806** are all examples of computer-readable storage media. For example, computer-readable storage media may include volatile and non-volatile, removable, and non-removable media implemented in any method or technology for storage of information, such as computer-readable instructions, data structures, program modules, or other data. Additional types of computer storage media that may be present may include, but are not limited to, programmable random access memory (PRAM), SRAM, DRAM, RAM, ROM, electrically erasable programmable read-only memory (EEPROM), flash memory, or other memory technology, compact disc read-only memory (CD-ROM), digital versatile discs (DVD) or other optical storage, magnetic cassettes, magnetic tapes, magnetic disk storage or other magnetic storage devices, or any other medium, which may be used to store the desired information and which may be accessed by the devices. Combinations of any of the above should also be included within the scope of computer-readable media.

The material controller **300** may also include one or more communication connection(s) that may facilitate a control device (not shown) to communicate with devices or equipment capable of communicating with the material controller **300**. The material controller **300** may also include a computer system (not shown). Connections may also be established via various data communication channels or ports, such as USB or COM ports to receive cables connecting the material controller **300** to various other devices on a network. In some examples, the material controller **300** may include Ethernet drivers that enable the material controller **300** to communicate with other devices on the network. According to various examples, communication connections **1808** may be established via a wired and/or wireless connection on the network.

The material controller **300** may also include one or more input devices **1810**, such as a keyboard, mouse, pen, voice input device, gesture input device, and/or touch input device. It may further include one or more output devices **1812**, such as a display, printer, and/or speakers. In some examples, computer-readable communication media may include computer-readable instructions, program modules, or other data transmitted within a data signal, such as a carrier wave or other transmission. As used herein, however, computer-readable storage media may not include computer-readable communication media.

Turning to the contents of the memory **1802**, the memory **1802** may include, but is not limited to, an operating system (OS) **1814** and one or more application programs or services for implementing the features and embodiments disclosed herein. Such applications or services may include remote

terminal units **1816** for executing certain systems and methods for controlling operation of the material extraction assembly **10** or material conveyance assembly **11** (e.g., semi- or full-autonomously controlling operation of the assembly), for example, upon receipt of one or more control signals generated by the material controller **300**. In some embodiments, one or more remote terminal unit(s) **1816** may be located on one or more components of the material extraction assembly **10** or material conveyance assembly **11**. The remote terminal unit(s) **1816** may reside in the memory **1802** or may be independent of the material controller **300**. In some examples, the remote terminal unit(s) **1816** may be implemented by software that may be provided in configurable control block language and may be stored in non-volatile memory. When executed by the processor(s) **1800**, the remote terminal unit(s) **1816** may implement the various functionalities and features associated with the material controller **300** described herein.

As desired, embodiments of the disclosure may include a material controller **300** with more or fewer components than are illustrated in FIG. 18. Additionally, certain components of the example material controller **300** shown in FIG. 18 may be combined in various embodiments of the disclosure. The material controller **300** of FIG. 18 is provided by way of example only.

References are made to block diagrams of systems, methods, apparatuses, and computer program products according to example embodiments. It will be understood that at least some of the blocks of the block diagrams, and combinations of blocks in the block diagrams, may be implemented at least partially by computer program instructions. These computer program instructions may be loaded onto a general purpose computer, special purpose computer, special purpose hardware-based computer, or other programmable data processing apparatus to produce a machine, such that the instructions which execute on the computer or other programmable data processing apparatus create means for implementing the functionality of at least some of the blocks of the block diagrams, or combinations of blocks in the block diagrams discussed.

These computer program instructions may also be stored in a non-transitory computer-readable memory that may direct a computer or other programmable data processing apparatus to function in a particular manner, such that the instructions stored in the computer-readable memory produce an article of manufacture including instruction means that implement the function specified in the block or blocks. The computer program instructions may also be loaded onto a computer or other programmable data processing apparatus to cause a series of operational steps to be performed on the computer or other programmable apparatus to produce a computer implemented process such that the instructions that execute on the computer or other programmable apparatus provide task, acts, actions, or operations for implementing the functions specified in the block or blocks.

One or more components of the systems and one or more elements of the methods described herein for FIG. 18 may be implemented through an application program running on an operating system of a computer. They may also be practiced with other computer system configurations, including hand-held devices, multiprocessor systems, microprocessor-based or programmable consumer electronics, mini-computers, mainframe computers, and the like.

Application programs that are components of the systems and methods described herein may include routines, programs, components, data structures, etc. that may implement certain abstract data types and perform certain tasks or

actions. In a distributed computing environment, the application program (in whole or in part) may be located in local memory or in other storage. In addition, or alternatively, the application program (in whole or in part) may be located in remote memory or in storage to allow for circumstances where tasks may be performed by remote processing devices linked through a communications network.

This application claims the benefit of and priority to U.S. Provisional Patent Application No. 63/373,289, filed Aug. 23, 2022, and titled "AIR COMPRESSOR HAVING VACUUM AND ASSOCIATED METHODS FOR LOADING AND EXTRACTING MATERIALS," the contents of which are incorporated herein by reference in their entirety.

This is a continuation-in-part of U.S. Non-Provisional application Ser. No. 17/811,277, filed Jul. 7, 2022, titled, "SYSTEMS, METHODS, AND DEVICES FOR INDUSTRIAL TOWER WASTE EXTRACTION," which claims priority to and the benefit of U.S. Provisional Application No. 63/367,570, filed Jul. 1, 2022, titled "HIGH VOLUME INDUSTRIAL VACUUM ASSEMBLIES AND METHODS," U.S. Provisional Application No. 63/367,219, filed Jun. 29, 2022, titled "RECEIVER, ASSEMBLIES, AND METHODS FOR LOADING AND EXTRACTING PRODUCT IN ELEVATED TOWER," U.S. Provisional Application No. 63/367,218, filed Jun. 29, 2022, titled "ASSEMBLIES AND METHODS FOR MATERIAL EXTRACTION FROM RETENTION COLLECTIONS," U.S. Provisional Application No. 63/364,630, filed May 13, 2022, titled "ASSEMBLIES, APPARATUSES, SYSTEMS, AND METHODS FOR MATERIAL EXTRACTION AND CONVEYANCE," U.S. Provisional Application No. 63/264,101, filed Nov. 16, 2021, titled "ASSEMBLIES AND METHODS FOR MATERIAL EXTRACTION," U.S. Provisional Application No. 63/264,015, filed Nov. 12, 2021, titled "ASSEMBLIES AND METHODS FOR MATERIAL EXTRACTION," U.S. Provisional Application No. 63/203,147, filed Jul. 9, 2021, titled "SYSTEMS, METHODS, AND DEVICES FOR INDUSTRIAL TOWER WASTE EXTRACTION," and U.S. Provisional Application No. 63/203,108, filed Jul. 8, 2021, titled "SYSTEMS, METHODS, AND DEVICES FOR INDUSTRIAL TOWER WASTE EXTRACTION," the disclosures of all of which are incorporated herein by reference in their entireties.

This application is also a continuation-in-part of U.S. Non-Provisional application Ser. No. 17/811,293, filed Jul. 7, 2022, titled, "ASSEMBLIES AND METHODS FOR MATERIAL EXTRACTION," which claims priority to and the benefit of U.S. Provisional Application No. 63/367,570, filed Jul. 1, 2022, titled "HIGH VOLUME INDUSTRIAL VACUUM ASSEMBLIES AND METHODS," U.S. Provisional Application No. 63/367,219, filed Jun. 29, 2022, titled "RECEIVER, ASSEMBLIES, AND METHODS FOR LOADING AND EXTRACTING PRODUCT IN ELEVATED TOWER," U.S. Provisional Application No. 63/367,218, filed Jun. 29, 2022, titled "ASSEMBLIES AND METHODS FOR MATERIAL EXTRACTION FROM RETENTION COLLECTIONS," U.S. Provisional Application No. 63/364,630, filed May 13, 2022, titled "ASSEMBLIES, APPARATUSES, SYSTEMS, AND METHODS FOR MATERIAL EXTRACTION AND CONVEYANCE," U.S. Provisional Application No. 63/264,101, filed Nov. 16, 2021, titled "ASSEMBLIES AND METHODS FOR MATERIAL EXTRACTION," U.S. Provisional Application No. 63/264,015, filed Nov. 12, 2021, titled "ASSEMBLIES AND METHODS FOR MATERIAL EXTRACTION," U.S. Provisional Application No. 63/203,147, filed Jul. 9, 2021, titled "SYSTEMS, METHODS, AND DEVICES FOR INDUSTRIAL TOWER WASTE EXTRACTION," U.S. Provisional Application No. 63/203,108, filed Jul. 8, 2021, titled "SYSTEMS, METHODS, AND DEVICES FOR INDUSTRIAL TOWER WASTE EXTRACTION," the disclosures of all of which are incorporated herein by reference in their entireties.

INDUSTRIAL TOWER WASTE EXTRACTION," and U.S. Provisional Application No. 63/203,108, filed Jul. 8, 2021, titled "SYSTEMS, METHODS, AND DEVICES FOR INDUSTRIAL TOWER WASTE EXTRACTION," the disclosures of all of which are incorporated herein by reference in their entireties.

This application is also a continuation-in-part of U.S. Non-Provisional application Ser. No. 17/811,295, filed Jul. 7, 2022, titled, "ASSEMBLIES, APPARATUSES, SYSTEMS, AND METHODS FOR MATERIAL EXTRACTION AND CONVEYANCE," which claims priority to and the benefit of U.S. Provisional Application No. 63/367,570, filed Jul. 1, 2022, titled "HIGH VOLUME INDUSTRIAL VACUUM ASSEMBLIES AND METHODS," U.S. Provisional Application No. 63/367,219, filed Jun. 29, 2022, titled "RECEIVER, ASSEMBLIES, AND METHODS FOR LOADING AND EXTRACTING PRODUCT IN ELEVATED TOWER," U.S. Provisional Application No. 63/367,218, filed Jun. 29, 2022, titled "ASSEMBLIES AND METHODS FOR MATERIAL EXTRACTION FROM RETENTION COLLECTIONS," U.S. Provisional Application No. 63/364,630, filed May 13, 2022, titled "ASSEMBLIES, APPARATUSES, SYSTEMS, AND METHODS FOR MATERIAL EXTRACTION AND CONVEYANCE," U.S. Provisional Application No. 63/264,101, filed Nov. 16, 2021, titled "ASSEMBLIES AND METHODS FOR MATERIAL EXTRACTION," U.S. Provisional Application No. 63/264,015, filed Nov. 12, 2021, titled "ASSEMBLIES AND METHODS FOR MATERIAL EXTRACTION," U.S. Provisional Application No. 63/203,147, filed Jul. 9, 2021, titled "SYSTEMS, METHODS, AND DEVICES FOR INDUSTRIAL TOWER WASTE EXTRACTION," and U.S. Provisional Application No. 63/203,108, filed Jul. 8, 2021, titled "SYSTEMS, METHODS, AND DEVICES FOR INDUSTRIAL TOWER WASTE EXTRACTION," the disclosures of all of which are incorporated herein by reference in their entireties.

This application is also a continuation-in-part of U.S. Non-Provisional application Ser. No. 17/811,280, filed Jul. 7, 2022, titled, "ASSEMBLIES AND METHODS FOR MATERIAL EXTRACTION FROM RETENTION COLLECTIONS," which claims priority to and the benefit of U.S. Provisional Application No. 63/367,570, filed Jul. 1, 2022, titled "HIGH VOLUME INDUSTRIAL VACUUM ASSEMBLIES AND METHODS," U.S. Provisional Application No. 63/367,219, filed Jun. 29, 2022, titled "RECEIVER, ASSEMBLIES, AND METHODS FOR LOADING AND EXTRACTING PRODUCT IN ELEVATED TOWER," U.S. Provisional Application No. 63/367,218, filed Jun. 29, 2022, titled "ASSEMBLIES AND METHODS FOR MATERIAL EXTRACTION FROM RETENTION COLLECTIONS," U.S. Provisional Application No. 63/364,630, filed May 13, 2022, titled "ASSEMBLIES, APPARATUSES, SYSTEMS, AND METHODS FOR MATERIAL EXTRACTION AND CONVEYANCE," U.S. Provisional Application No. 63/264,101, filed Nov. 16, 2021, titled "ASSEMBLIES AND METHODS FOR MATERIAL EXTRACTION," U.S. Provisional Application No. 63/264,015, filed Nov. 12, 2021, titled "ASSEMBLIES AND METHODS FOR MATERIAL EXTRACTION," U.S. Provisional Application No. 63/203,147, filed Jul. 9, 2021, titled "SYSTEMS, METHODS, AND DEVICES FOR INDUSTRIAL TOWER WASTE EXTRACTION," and U.S. Provisional Application No. 63/203,108, filed Jul. 8, 2021, titled "SYSTEMS, METHODS, AND DEVICES FOR INDUSTRIAL TOWER WASTE EXTRACTION," the disclosures of all of which are incorporated herein by reference in their entireties.

FOR INDUSTRIAL TOWER WASTE EXTRACTION," the disclosures of all of which are incorporated herein by reference in their entireties.

This application is also a continuation-in-part of U.S. Non-Provisional application Ser. No. 17/811,291, filed Jul. 7, 2022, titled, "HIGH VOLUME INDUSTRIAL VACUUM ASSEMBLIES AND METHODS," which claims priority to and the benefit of U.S. Provisional Application No. 63/367,570, filed Jul. 1, 2022, titled "HIGH VOLUME INDUSTRIAL VACUUM ASSEMBLIES AND METHODS," U.S. Provisional Application No. 63/367,219, filed Jun. 29, 2022, titled "RECEIVER, ASSEMBLIES, AND METHODS FOR LOADING AND EXTRACTING PRODUCT IN ELEVATED TOWER," U.S. Provisional Application No. 63/367,218, filed Jun. 29, 2022, titled "ASSEMBLIES AND METHODS FOR MATERIAL EXTRACTION FROM RETENTION COLLECTIONS," U.S. Provisional Application No. 63/364,630, filed May 13, 2022, titled "ASSEMBLIES, APPARATUSES, SYSTEMS, AND METHODS FOR MATERIAL EXTRACTION AND CONVEYANCE," U.S. Provisional Application No. 63/264,101, filed Nov. 16, 2021, titled "ASSEMBLIES AND METHODS FOR MATERIAL EXTRACTION," U.S. Provisional Application No. 63/264,015, filed Nov. 12, 2021, titled "ASSEMBLIES AND METHODS FOR MATERIAL EXTRACTION," U.S. Provisional Application No. 63/203,147, filed Jul. 9, 2021, titled "SYSTEMS, METHODS, AND DEVICES FOR INDUSTRIAL TOWER WASTE EXTRACTION," and U.S. Provisional Application No. 63/203,108, filed Jul. 8, 2021, titled "SYSTEMS, METHODS, AND DEVICES FOR INDUSTRIAL TOWER WASTE EXTRACTION," the disclosures of all of which are incorporated herein by reference in their entireties.

This application is also a continuation-in-part of U.S. Non-Provisional application Ser. No. 17/811,288, filed Jul. 7, 2022, titled, "RECEIVER, ASSEMBLIES, AND METHODS FOR LOADING AND EXTRACTING PRODUCT IN ELEVATED TOWER," which claims priority to and the benefit of U.S. Provisional Application No. 63/367,570, filed Jul. 1, 2022, titled "HIGH VOLUME INDUSTRIAL VACUUM ASSEMBLIES AND METHODS," U.S. Provisional Application No. 63/367,219, filed Jun. 29, 2022, titled "RECEIVER, ASSEMBLIES, AND METHODS FOR LOADING AND EXTRACTING PRODUCT IN ELEVATED TOWER," U.S. Provisional Application No. 63/367,218, filed Jun. 29, 2022, titled "ASSEMBLIES AND METHODS FOR MATERIAL EXTRACTION FROM RETENTION COLLECTIONS," U.S. Provisional Application No. 63/364,630, filed May 13, 2022, titled "ASSEMBLIES, APPARATUSES, SYSTEMS, AND METHODS FOR MATERIAL EXTRACTION AND CONVEYANCE," U.S. Provisional Application No. 63/264,101, filed Nov. 16, 2021, titled "ASSEMBLIES AND METHODS FOR MATERIAL EXTRACTION," U.S. Provisional Application No. 63/264,015, filed Nov. 12, 2021, titled "ASSEMBLIES AND METHODS FOR MATERIAL EXTRACTION," U.S. Provisional Application No. 63/203,147, filed Jul. 9, 2021, titled "SYSTEMS, METHODS, AND DEVICES FOR INDUSTRIAL TOWER WASTE EXTRACTION," and U.S. Provisional Application No. 63/203,108, filed Jul. 8, 2021, titled "SYSTEMS, METHODS, AND DEVICES FOR INDUSTRIAL TOWER WASTE EXTRACTION," the disclosures of all of which are incorporated herein by reference in their entireties.

Having now described some illustrative embodiments of the disclosure, it should be apparent to those skilled in the art that the foregoing is merely illustrative and not limiting,

having been presented by way of example only. Numerous modifications and other embodiments are within the scope of one of ordinary skill in the art and are contemplated as falling within the scope of the disclosure. In particular, although many of the examples presented herein involve specific combinations of method acts or system elements, it should be understood that those acts and those elements may be combined in other ways to accomplish the same objectives. Those skilled in the art should appreciate that the parameters and configurations described herein are exemplary and that actual parameters and/or configurations will depend on the specific application in which the systems, methods, and/or aspects or techniques of the disclosure are used. Those skilled in the art should also recognize or be able to ascertain, using no more than routine experimentation, equivalents to the specific embodiments of the disclosure. It is, therefore, to be understood that the embodiments described herein are presented by way of example only and that, within the scope of any appended claims and equivalents thereto, the disclosure may be practiced other than as specifically described.

Furthermore, the scope of the present disclosure shall be construed to cover various modifications, combinations, additions, alterations, etc., above and to the above-described embodiments, which shall be considered to be within the scope of this disclosure. Accordingly, various features and characteristics as discussed herein may be selectively interchanged and applied to other illustrated and non-illustrated embodiment, and numerous variations, modifications, and additions further may be made thereto without departing from the spirit and scope of the present disclosure as set forth in the appended claims.

What is claimed is:

1. An extraction assembly to enhance extraction of material from a material source, the extraction assembly comprising:
  - a compressor and vacuum generation assembly comprising:
  - a compressor housing,
  - one or more compressors in the compressor housing,
  - one or more electric motors connected to the one or more compressors,
  - one or more vacuum controllers, and
  - one or more vacuum generators at least partially contained in the compressor housing and connected to the one or more compressors, the one or more vacuum generators positioned to generate a vacuum flow; and
  - a sound attenuation chamber including an attenuation housing at least partially defining a chamber interior volume positioned to receive at least a portion of the vacuum flow from the one or more vacuum generators and attenuate sound generated by operation of the one or more vacuum generators.
2. An extraction assembly to enhance extraction of material from a material source, the extraction assembly comprising:
  - a compressor and vacuum generation assembly comprising:
  - a compressor housing,
  - one or more compressors in the compressor housing,
  - one or more electric motors connected to the one or more compressors,
  - one or more vacuum controllers, and
  - one or more vacuum generators at least partially contained in the compressor housing and connected to

49

- the one or more compressors, the one or more vacuum generators positioned to generate a vacuum flow;
- at least one manifold connected to the material source and positioned to provide a flow path to convey extracted material from the material source to a material collector; and
- a sound attenuation chamber including an attenuation housing at least partially defining a chamber interior volume positioned to receive at least a portion of the vacuum flow from the one or more vacuum generators and attenuate sound generated by operation of the one or more vacuum generators.
3. An extraction assembly to enhance extraction of material from a material source, the extraction assembly comprising:
- a compressor and vacuum generation assembly comprising:
- a compressor housing,
- one or more compressors in the compressor housing, 20
- one or more electric motors connected to the one or more compressors,
- one or more vacuum controllers, and
- one or more vacuum generators at least partially contained in the compressor housing and connected to the one or more compressors, the one or more vacuum generators comprising a venturi mechanism configured to receive pressurized fluid from the one or more compressors and use a venturi effect to generate a vacuum flow between the material source 25 and the sound attenuation chamber; and
- a sound attenuation chamber including an attenuation housing at least partially defining a chamber interior volume positioned to receive at least a portion of the vacuum flow and attenuate sound generated by operation of the one or more vacuum generators.
4. An extraction assembly to enhance extraction of material from a material source, the extraction assembly comprising:
- a compressor and vacuum generation assembly comprising- 40
- a compressor housing,
- one or more compressors in the compressor housing, at least one of the one or more compressors comprising a screw compressor,
- one or more electric motors connected to the one or more compressors,
- one or more vacuum controllers, and
- one or more vacuum generators at least partially contained in the compressor housing and connected to the one or more compressors, the one or more vacuum generators positioned to generate a vacuum flow; and
- a sound attenuation chamber including an attenuation housing at least partially defining a chamber interior volume positioned to receive at least a portion of the vacuum flow from the one or more vacuum generators and attenuate sound generated by operation of the one or more vacuum generators.
5. The extraction assembly of claim 1, wherein the compressor and vacuum generation assembly and the sound attenuation chamber are mounted to a common chassis.
6. The extraction assembly of claim 5, wherein the common chassis is configured to be transported between geographical locations.
7. The extraction assembly of claim 1, wherein the one or more vacuum generators is connected to a material collector,

50

- the material collector configured such that the vacuum flow passes through the material collector, thereby to draw the extracted material into the material collector.
8. The extraction assembly of claim 7, wherein the one or more vacuum generators is configured to draw a minor portion of the extracted material into the sound attenuation chamber and deposit a major portion of the extracted material in the material collector.
9. An extraction assembly to enhance extraction of material from a material source, the extraction assembly comprising:
- a compressor and vacuum generation assembly comprising:
- a compressor housing,
- one or more compressors in the compressor housing, 10
- one or more electric motors connected to the one or more compressors,
- one or more vacuum controllers, and
- one or more vacuum generators at least partially contained in the compressor housing and connected to the one or more compressors, the one or more vacuum generators comprising a venturi mechanism configured to receive pressurized fluid from the one or more compressors and use a venturi effect to generate a vacuum flow between the material source and a material collector configured to collect a portion of material extracted from the material source; and
- a sound attenuation chamber including an attenuation housing at least partially defining a chamber interior volume being positioned to receive at least a portion of the vacuum flow and attenuate sound generated by operation of the one or more vacuum generators.
10. An extraction assembly to enhance extraction of material from a material source, the extraction assembly comprising:
- a compressor and vacuum generation assembly comprising:
- a compressor housing,
- one or more compressors in the compressor housing, 20
- one or more electric motors connected to the one or more compressors,
- one or more vacuum controllers, and
- one or more vacuum generators at least partially contained in the compressor housing and connected to the one or more compressors, the one or more vacuum generators comprising a first vacuum source and positioned to generate a vacuum flow;
- a manifold connected to the material source and positioned to provide a flow path to convey extracted material from the material source;
- a first material collector connected to the manifold and configured to collect a portion of the extracted material;
- a second material collector connected to the manifold;
- a second vacuum source connected to the second material collector, the first vacuum source, the second vacuum source, the first material collector, and the second material collector configured to increase an extraction rate of the material from the material source; and
- a sound attenuation chamber including an attenuation housing at least partially defining a chamber interior volume positioned to receive at least a portion of the vacuum flow from the one or more vacuum generators and attenuate sound generated by operation of the one or more vacuum generators.
11. The extraction assembly of claim 1, wherein one or more of the plurality of vacuum generators comprises one or

51

more exhaust ports, the one or more exhaust ports to provide fluid flow from the one or more vacuum generators to the sound attenuation chamber.

12. An extraction assembly to enhance extraction of material from a material source, the extraction assembly comprising:

- a compressor and vacuum generation assembly comprising:
- a compressor housing,
- one or more compressors in the compressor housing, 10
- one or more electric motors connected to the one or more compressors,
- one or more vacuum controllers, and
- one or more vacuum generators at least partially contained in the compressor housing and connected to the one or more compressors, the one or more vacuum generators positioned to generate a vacuum flow, and the one or more vacuum controllers configured to control one or more of:
- (a) one or more fluid supply control valves associated 20 with the one or more vacuum generators,
- (b) an exhaust control valve to control a vacuum pressure generated by the one or more vacuum generators,
- (c) one or more operating setpoints of the one or more 25 electric motors, or
- (d) one or more operating setpoints of the one or more compressors; and

a sound attenuation chamber including an attenuation housing at least partially defining a chamber interior volume positioned to receive at least a portion of the vacuum flow from the one or more vacuum generators and attenuate sound generated by operation of the one or more vacuum generators.

13. The extraction assembly of claim **12**, wherein the one or more vacuum controllers is configured to control a vacuum pressure generated by the one or more vacuum generators at least partially responsive to one or more of:

- (1) an operator setting, or
- (2) a sensor signal indicative of one or more of:
- the vacuum pressure,
- a temperature,
- a relative moisture;
- a vacuum flow rate, or
- a parameter related to the material extracted from the 45 material source.

14. An extraction assembly to enhance extraction of material from a material source, the extraction assembly comprising:

- a compressor and vacuum generation assembly comprising:
- a compressor housing,
- one or more compressors in the compressor housing,
- one or more electric motors connected to the one or more compressors,
- one or more vacuum controllers, and
- one or more vacuum generators at least partially contained in the compressor housing and connected to the one or more compressors, the one or more vacuum generators comprising two or more venturis positioned to generate a vacuum flow, the two or more venturis configured to operate in parallel to enhance vacuum pressure generated by the one or more vacuum generators; and

a sound attenuation chamber including an attenuation housing at least partially defining a chamber interior volume positioned to receive at least a portion of the

52

vacuum flow from the one or more vacuum generators and attenuate sound generated by operation of the one or more vacuum generators.

15. An extraction assembly to enhance extraction of material from a material source, the extraction assembly comprising:

- a compressor and vacuum generation assembly comprising:
- a compressor housing,
- one or more compressors in the compressor housing,
- one or more electric motors connected to the one or more compressors,
- one or more vacuum controllers, and
- one or more vacuum generators at least partially contained in the compressor housing and connected to the one or more compressors, the one or more vacuum generators comprising four or more venturis positioned to generate a vacuum flow, the four or more venturis configured to operate in parallel to enhance vacuum pressure generated by the vacuum source; and

a sound attenuation chamber including an attenuation housing at least partially defining a chamber interior volume positioned to receive at least a portion of the vacuum flow from the one or more vacuum generators and attenuate sound generated by operation of the one or more vacuum generators.

16. The extraction assembly of claim **1**, further comprising filter media at least partially enclosed in the sound attenuation chamber and configured to filter a portion of the material extracted from the material source from the vacuum flow passing through the sound attenuation chamber.

17. The extraction assembly of claim **1**, wherein the material source comprises a tower of a refinery apparatus.

18. An extraction assembly to enhance extraction of material from a material source, the extraction assembly comprising:

- a compressor and vacuum generation assembly comprising:
- a compressor housing,
- a cooling system in the compressor housing configured to remove heat from an interior of the compressor housing,
- one or more compressors in the compressor housing,
- one or more electric motors connected to the one or more compressors,
- one or more vacuum controllers, and
- one or more vacuum generators at least partially contained in the compressor housing and connected to the one or more compressors, the one or more vacuum generators positioned to generate a vacuum flow; and

a sound attenuation chamber including an attenuation housing at least partially defining a chamber interior volume positioned to receive at least a portion of the vacuum flow from the one or more vacuum generators and attenuate sound generated by operation of the one or more vacuum generators.

19. The extraction assembly of claim **18**, wherein the cooling system comprises one or more after coolers, the one or more after coolers comprising one or more heat exchange surfaces.

20. The extraction assembly of claim **19**, wherein the cooling system further comprises a fan configured to force air through the one or more heat exchange surfaces to remove heat from the compressor housing.

21. An extraction assembly to enhance extraction of material from a material source, the extraction assembly comprising:

a compressor and vacuum generation assembly comprising:

a compressor housing,

one or more compressors in the compressor housing,

one or more electric motors connected to the one or more compressors,

one or more vacuum controllers,

one or more vacuum generators at least partially contained in the compressor housing and connected to the one or more compressors, the one or more vacuum generators positioned to generate a vacuum flow, and

a moisture separator in the compressor housing configured to remove moisture from the vacuum flow;

and

a sound attenuation chamber including an attenuation housing at least partially defining a chamber interior volume positioned to receive at least a portion of the vacuum flow from the one or more vacuum generators and attenuate sound generated by operation of the one or more vacuum generators.

22. The extraction assembly of claim 1, wherein the material comprises one or more of catalyst, pall rings, beads, balls, pellets, sand, or bricks.
